UNITED STATES PATENT OFFICE.

HERBERT M. FRIENDLY, OF PORTLAND, OREGON.

AUTOMATIC TELEPHONE SYSTEM.

Application filed May 3, 1921. Serial No. 466,433.

The present invention relates in general to automatic telephone systems, but is more particularly concerned with small automatic systems of the type which are used to a great extent in factories, commercial establishments, and the like. Systems of this type are well known under the name of private automatic exchanges.

One of the principal objects of the invention is to provide a private automatic exchange system which will operate without change in conjunction with either a manual or automatic main exchange. This is important in view of the fact that a great many manual telephone systems are now being replaced by automatic systems and in all probability all manual systems will be so replaced. It will be seen therefore that a great advantage is obtained if the circuits of the private automatic exchanges are so designed that when the main exchange service is changed from manual to automatic the private automatic exchange equipment can still be used without having to revise the circuits in any particular.

In carrying out the general object above set forth a large number of new features have been incorporated in the system, the principal ones of which will be briefly pointed out below:

In private automatic exchange systems it is desirable when a subscriber in the main exchange calls a subscriber in the private automatic exchange to provide means whereby the connection may be passed or transferred to another party; and that this transferring operation may be performed by either the calling subscriber (if he is located in an automatic exchange) or the called subscriber. It will be apparent that where the private automatic exchange is large say of from 500 to 1000 or more subscribers the cost of furnishing this transfer call service to all the subscribers may become prohibitive. According to the present invention somewhat less than 100 subscribers in a large private automatic exchange are given this class of service. In the city directory are listed only the names of these subscribers. Now, when one of these is called by a main exchange subscriber if it should be

found that another party in the branch exchange is desired, the called subscriber may, by operating his calling device, extend the connection to the party desired, if it is one of the selected group of subscribers. However, should it be one of the other subscribers in the private automatic exchange, the called subscriber is able to signal an attendant operator. The attendant operator has a multiple of all local lines before her and after ascertaining the number of the desired local station she may extend the connection to that line manually. When the calling subscriber in the main exchange does not find the number of the particular subscriber in the private automatic exchange he desires listed in the directory, he may call the attendant operator who, after ascertaining his wants will extend the connection to the desired local subscriber. In this manner while all the branch exchange subscribers may be reached from the main exchange the expensive and complicated automatic passing call apparatus is supplied only for a small number of subscribers.

A further feature of the invention relates to an improved night service arrangement whereby a plug ending trunk extending from a main exchange to a branch exchange is connected to a local line. When the trunk is seized from the main exchange ringing current is automatically projected out on the preconnected local line until an answer is obtained. When this occurs the subscriber called may pass or transfer the call to another party in the branch exchange.

Another object provides means so that when the trunk line is not in use the preconnected branch exchange substation may call and be called and also whenever it becomes busy a busy potential is applied to the trunk line in the main exchange.

Still another feature provides new and improved means for preventing any calls made on an incoming trunk line to the branch exchange from being completed without the intervention of the attendant operator.

Further objects relate to means for restricting the calling of certain lines or certain groups of lines to main exchange subscribers, though at the same time they are

still accessible to the attendant. This restriction may be optionally controlled from certain of the local substations.

Further features relate to the provision of a special busy release circuit of the automatic switches used in transferring the call; to the provision of new supervisory circuits whereby the attendant and main exchange operators (provided the main exchange is operating manually) are notified of the various operations; and to provide special circuits for signalling the operator in the branch exchange.

There are a number of other features not now specifically mentioned which together with the foregoing will be described herein-after, with reference to the accompanying drawings.

Referring now to the drawings, in Fig. 1 is shown a schematic trunking diagram of an automatic exchange system of the above character.

Figs. 2 and 2^A show in general the equipment in both the manual and automatic main exchange, the apparatus in the manual exchange being shown in the lower portion of the sheet and consisting of a cord circuit O and the equipment associated with the trunk line which terminates in the jack J. The automatic apparatus is shown in the upper portion of the sheet and consists of a selector repeater indicated diagrammatically at E, the line switch C, of the well known plunger type which is associated with the trunk line comprising conductors 51 and 52 extending to the branch exchange. The line switch C is one of a group of line switches all adapted to be controlled in the well known manner by a master switch (not shown) the function of which is to maintain the plungers of all idle line switches opposite an idle trunk line. The line switch C and similar line switches have access to first selectors one of which is indicated at D. The key K⁴ is adapted to transfer the trunk line extending to the private automatic exchange from manual to automatic operation, when the manual exchange is cut over to automatic use.

Figs. 3 and 4 show the trunk line comprising conductors 51 and 52 extending into the private automatic exchange and also the trunk equipment associated with this trunk line in the attendant's cabinet. The jack J³ is a terminal of the trunk line accessible to the attendant operator and is used by the attendant in extending the local subscribers' lines to the main exchange. The plug P² is used for night service and also for transferring a connection from the trunk line to a local substation.

In Figs. 5, 6, 7 and 8 are shown two dual connector switches in which the incoming trunk line terminates. These connectors are of the usual type used for passing calls each

having access to local subscribers' lines and trunk lines extending to an isolated private branch exchange. The bank contacts 615-618 being the terminal of such a trunk line in the main connector H and having the multiple bank contacts 390-393, inclusive, accessible to the auxiliary connector H'. The bank contacts 620-623, inclusive, in the main connector H are associated with the line of the substation A⁵ while the bank contacts 625-628, inclusive, are associated with the line of the substation A⁴. These bank contacts are of course multiplied in the usual manner in the auxiliary dual connector switch H' and all other local connector switches which have access to the lines of these substations.

The substations A⁴ and A⁵, Fig. 9 and also the trunk line extending to the private branch exchange, Fig. 10, have individual line switches of the plunger type associated therewith. These line switches are adapted to be controlled by a master switch (not shown) in the well known manner. The jacks J⁶, J⁷ and J⁵ enable the attendant operator to connect manually with the substations A⁴ and A⁵ and the trunk line extending to the private branch exchange, respectively.

The equipment in the isolated branch exchange is shown in Fig. 10 and consists of a cord circuit O' and a manual substation A⁷ the latter having the usual line equipment associated with it. The trunk lines accessible to the line switches C⁴, C⁵ and C⁷ terminate in the local first selector switches one of which is shown at D², Fig. 11. This selector is of the usual Strowger type having access to trunk lines leading to the attendant operator from the first level while from the second level the trunk lines lead to local connector selector repeaters one of which is shown at H². From the third and other levels of the first selectors the trunk lines lead to local connector switches of the usual type. These switches have access to local subscribers' lines only, and consequently their operation is similar to that of the connector switch H² on the third to the eighth levels, inclusive, where it also has access to local subscribers' lines. The connector H² is of the well known Strowger vertical and rotary type and has the usual set of 100 bank contacts arranged in ten groups or levels. From the third to the eighth level this switch functions as an ordinary connector switch and has access to local subscribers' lines. On the first and second levels the connector has access to trunk lines leading to the information and complaint operators in the private automatic exchange. On the ninth level the connector selector repeaters have access to trunk lines leading to the private branch exchange, while on the tenth level these switches have

access to trunk lines leading to the main exchange. The substation A³ which is accessible to the connector selector repeater H² has the individual line switch C⁸ and the individual line jack J¹⁰.

In Fig. 11^a is shown a mechanical interlocking device which is adapted to be used on certain relays in the local connector selector repeaters such as H².

Fig. 11^b shows a detail of the shaft of Fig. 11 with relation to the cam-springs 909-912 and 905-908.

Fig. 12 shows the cord circuit used by the attendant operator for interconnecting local lines.

Fig. 13 shows the manner in which certain sheets of drawings should be placed in order to obtain a complete view of the system.

Figs. 14, 15, and 16 show the trunk circuits of the complaint, information, and attendant operators, respectively, whereby these operators may be signalled by the local private automatic exchange subscribers.

In Fig. 17 is shown the cord circuit which the attendant operator may use to extend a call received from a trunk circuit to the main exchange subscriber by way of the jack J² or similar jacks.

Fig. 18 shows a modification of the cord circuit O used by the main exchange operator whereby the supervision is controlled in a different manner.

In Fig. 19 is shown the cord circuit used for interconnecting local substations in the isolated branch exchange.

Fig. 20 shows certain improvements which relate to the night service circuits and will be discussed more in detail hereinafter.

Fig. 21 shows a cord circuit which is adapted to be used by the attendant operator in the private automatic exchange when the main exchange is operating manually.

The manner in which a connection local to the main exchange is completed will now be described generally with reference to Fig. 1. For this purpose it will be assumed that the subscriber at substation A desires to call the subscriber at substation A'. Under these conditions the calling subscriber will remove his receiver and operate his calling device for the digits of the number assigned to the subscriber at substation A'. By these operations the line switch individual to the calling subscriber's line operates to automatically select an idle trunk leading to a first selector such as D. This first selector D is then operated in response to the first digit of the desired subscriber's number to the proper level and then automatically rotates to select an idle trunk terminating in a second selector such as D'. The selector D' is operated opposite the level corresponding to the second digit called by the calling subscriber and in the same manner as the first selector D operates to select an idle

connector switch which has access to the line of the subscriber at substations A and A' which it will be assumed is the connector indicated diagrammatically at H⁴. In response to the last two digits of the called subscriber's number the connector H⁴ is operated in the usual manner into engagement with the desired subscriber's line. After the conversation is terminated the connection is released in the usual automatic manner by the calling subscriber replacing his receiver upon the switchhook.

It will now be assumed that the subscriber at substation A desires to establish a connection with the subscriber at substation A⁴ so in the private automatic exchange. When the receiver is removed the rotary line switch individual to the line of the substation A operates as before to select a trunk line leading to an idle first selector such as D similarly to the switch C. When the first digit of the number in the private automatic exchange is called the selector D is operated for the proper level and rotates to automatically select an idle selector repeater such as the switch E. In response to the second digit dialled by the calling subscriber the selector repeater E is operated opposite the level in which the trunk lines are terminated leading to the private automatic exchange. In the usual manner the switch E then operates to select an idle one of these trunk lines, which we will assume is the trunk line shown extending through the attendant's cabinet N at the private automatic exchange and terminating in dual connectors H and H'. In response to the last two digits of the number of the substation A⁴ the main connector H is operated into engagement with the bank contacts associated with the line of the subscriber. If the called subscriber's line happens to be busy at this time the main connector H will be automatically released and the calling subscriber given the busy signal.

There is now open to the calling subscriber two courses, one of which is to replace his receiver on the switchhook thereby releasing the operated switches in the well known manner or he may by operating his calling device for the last two digits of another branch exchange subscriber's number operate the auxiliary connector H' into connection with this other subscriber's line. If it should be found after conversing with the called branch exchange subscriber that another party in the branch exchange is desired either the calling or the called subscriber may by operating his calling device cause the main connector H to be operated into connection with the desired subscriber's line. In the former case the first digit dialled by the calling subscriber serves to release the auxiliary connector H'. In the latter case the connector H' is not automatically released. Should this subscriber's line happen

to be busy, the main connector H will be automatically released and the first called subscriber may reoperate it if he so desires. After connection is made with the desired second branch exchange subscriber's line the first called party by replacing his receiver upon the switchhook will release the auxiliary connector switch H'. However, if he holds the line until the second called subscriber answers a three party conference may be held. At the termination of this conference either called party by operating his calling device is enabled to release the connection to the other branch exchange subscriber's line. Should the first called subscriber replace his receiver upon the switchhook he will release the auxiliary connector H' and in a like manner the second called subscriber upon hanging up would release the main connector H.

It may now happen that another subscriber in the private automatic exchange is desired whose line is not accessible to the dual connector switches H and H'. Under these conditions, it will be necessary to signal the attendant operator and have her complete the connection manually. In order to signal the operator, the called subscriber will operate his calling device for the digit 1, thereby causing the auxiliary connector switch to step to the first level and then be automatically released. By these operations the line lamp associated with the trunk line in the attendant's cabinet will be lighted and the attendant operator will throw her listening key in order to ascertain the number of the subscriber desired. After finding out the number of the desired subscriber's line the operator will insert the plug P² associated with the trunk line into the jack of a local substation. This line will then be automatically signalled.

When this last called subscriber answers he will be in communication with the calling subscriber in the main exchange and the other called subscriber in the private automatic exchange. The last called party has also control of the dual connector H in the same manner as if he were called through the medium of a dual switch. Thus by operating his calling device he may release the main connector H or by hanging up his receiver disassociate his line completely from the incoming trunk line, also the other called subscriber in the branch exchange is enabled by operating his calling device to disassociate the subscriber called by means of the plug from the connection.

Under certain conditions it is desirable that certain lines in the private automatic exchange may be made inaccessible to the calling subscriber. In this case, when he attempts to operate one of the dual connectors H or H' into engagement with this "barred" line the operated connector switch

will be automatically released and a distinctive tone given to the calling subscriber in order to inform him that he is unable to connect with this line. However, the calling subscriber may connect with the "non-barred" line and request the called subscriber to place him in connection with the "barred" line. The called subscriber will be able to do this as the "barred" line is not inaccessible to a private automatic exchange subscriber.

Instead of signalling one of the branch exchange subscribers to extend his connection to a "barred" telephone the calling subscriber might by operating his calling device for the digit 0, operate the auxiliary connector switch H' to the tenth level whereupon it would be automatically released. By these operations the attendant operator is again signalled. She may then by operating her calling device or by using the night plug P² associated with the trunk line extend the connection to the line of the "barred" subscriber. When the connection is finally terminated the calling subscriber by replacing his receiver upon the switchhook will cause the release of the operated switches in the well known manner.

The attendant operator in the private automatic exchange may for certain reasons desire to extend all calls received over the trunk lines to the desired branch exchange subscriber. In order to do this she will restore one of her keys to normal. Now when a subscriber in the main exchange such as the one at substation A connects with the trunk line terminating in the dual switches H and H' he will be unable to operate the switches and a line lamp will appear before the operator. She may complete the connection through automatically by way of the dual switches or manually by way of the night plug P². If the call is extended automatically, when the called subscriber answers the connection may be transferred by that subscriber in the usual manner to any of the branch exchange subscribers accessible to the dual switches by way of the main connector associated with the trunk line.

The dual connectors also have access to trunk lines leading to an isolated private branch exchange, this being shown immediately below and to the right of the dotted lines in the lower right hand corner of the sheet. If the calling subscriber had desired connection with this private branch exchange the attendant could have operated the main dual connector H into engagement with the trunk line extending to this exchange. By this operation the operator in the private branch exchange would be signalled and she will answer the call by inserting the plug of the cord circuit, such

as the cord circuit O', into the jack J⁸ and after ascertaining the number of the local subscriber desired, extend the call to that subscriber by way of the calling end of the 6 cord circuit. After the conversation is terminated both subscribers will replace their receivers upon the switchhook. When the receiver is replaced at the calling substation A in the main exchange the operated 10 switches are released and the private automatic exchange and the branch exchange operators are given the supervisory signal. When the called subscriber replaces his receiver upon the switchhook another supervisory signal in the cord circuit O' is operated 15 and local branch exchange operator is thereby notified that the conversation is terminated and she will withdraw the plugs of the cord circuit O' from the associated jacks. 20 There are a number of special connections when the calling subscribers in the main exchange are only allowed a limited use of the dual connector switches H and H'. When it is desired that this class of service 25 should be given, the attendant operator in the private automatic exchange will operate certain keys associated with the incoming trunk lines. The operation when a calling subscriber in the main exchange connects 30 with one of these trunk lines under these conditions will now be briefly described.

Again it will be assumed that the calling subscriber is at substation A in the main exchange and is connected to the trunk line 35 associated with the switches H and H' by way of the individual line switch C, selector D and selector repeater E. When the calling device at the calling substation is operated for the next two digits the main 40 connector H is operated into engagement with the desired called subscriber's line which it will be assumed is that of the substation A⁴. If connection is made there- 45 with the calling subscriber is prevented from passing the call and has to release and in order to establish a new connection if another branch exchange subscriber is desired, provided of course the subscriber at 50 substation A⁴ does not answer.

55 Should one of the other keys at the attendant operator's position be thrown the calling subscriber may control the dual switches until a branch exchange subscriber answers after which the calling subscriber is prevented from passing the call. In both the above cases either of the called subscribers upon answering could transfer the call in the usual manner. In either case after 60 the conversation is terminated the release will take place in the ordinary manner.

Under certain conditions the calling subscriber may find it desirable to signal the attendant operator in the branch exchange directly. In order to do this if the trunk 65 line extending to the branch automatic ex-

change is busy he will operate his calling device for a particular digit thereby causing the main dual connector switch to step to a certain level and then release. These operations will signal the attendant operator who will attend to his wants in the usual manner.

In the above descriptions was stated in a general way the ordinary connections from the main to the branch exchange when the 75 attendant operator is on duty. At night, however, the attendant operator is not at her position and some provision must be made to handle calls coming into the private automatic exchange. In order to do this 80 the night plug associated with the incoming trunk line is inserted into the jack of the substation which is to be connected for night service and at which the watchman or some other employee is located during the 85 time when the trunk is connected for night service. For the purpose of description it will again be assumed that the calling subscriber at substation A has seized one of the trunk lines extending to the branch ex- 90 change and terminating in dual connectors H and H'. When such a night connection is up immediately upon the trunk line being seized the "pre-connected" local substation is automatically signalled. Upon an- 95 swering the subscriber at this telephone has complete control of the main dual switch H and may pass the call by this means. It might have happened that the subscriber in the main exchange desired a particular 100 party in the branch exchange with which he desired to obtain connection during the night. Immediately upon seizing the trunk line the automatic ringing of the "pre-con- 105 nected" local line would begin but upon the first impulse in the next digit dialled by the calling subscriber the night plug P² is completely disassociated from the trunk line and the dual connectors may be controlled by the calling subscriber in the ordinary 110 manner.

While the local substation is thus connected up for night service it may be called by a local subscriber such as the one at substation A⁶ through the medium of the individual line 115 switch C⁶, and a local branch exchange first selector such as D², and a local connector which has access to the line of the substation A⁶. The preconnected substation is also able to call through the medium of the individual line switch. During the time when this substation is seized either for the reason that it is calling or being called the associated trunk line with which it is connected for night service is busied in the 120 main exchange.

When the main exchange is operating manually all the connections above described may be set up and controlled by a main exchange operator though in this case there 125 130

are a number of novel features involved in this operation which will be described fully later in the detailed description.

Having described generally the connections in the main exchange and from the main to the branch exchange a few local calls individual to the private automatic exchange will now be described in a general manner. The local connections between 10 private automatic exchange subscribers have been described hereinbefore and so it will be unnecessary to describe them at this point.

It is often necessary for the private automatic exchange subscribers to obtain information of varying nature. In order to provide for this class of service there is an information operator in the private automatic exchange. When a calling subscriber such as the one at substation A⁴ desires to call 15 this operator he will remove his receiver and operate his calling device for two digits of the number of the information operator, which in this case is 22. By these operations the individual line switch C⁴ is operated to 20 select an idle first selector similar to D² which seized switch is then operated to the second level and automatically selects a trunk line extending to an idle local connector switch such as the switch H². In response to the last digit the connector H² is 25 raised to the second level and operates to automatically select a trunk line extending to the information operator located at the operator's position N'. 30

Had the complaint operator in the private automatic exchange been desired the connector switch would have been raised to the first level instead of the second and then would automatically rotate to select a trunk 35 leading to the complaint operator who is also located at the operator's position N'.

Should the calling subscriber at substation A⁴ desire to obtain the attendant operator he may by removing his receiver and operating his calling device for the digit 1 extend 40 a connection to the attendant. By these operations the line switch C⁴ and the selector D² are operated as before described, the selector D² being raised to the first level 45 after which it automatically rotates to select an idle trunk line leading to the attendant operator's position N. The attendant operator will insert the plug of an idle cord circuit into the jack of this trunk line and 50 throw her listening key in order to ascertain what is desired. It may happen that the calling subscriber desires a connection at a later time with another branch exchange subscriber and he requests the operator to obtain 55 this connection for him. At the predetermined time the operator will insert the plugs of an idle cord circuit such as the cord circuit shown in Fig. 12 into the jack of the calling substation and that of the desired 60 called substation and then operate her ring-

ing keys. When this party answers the operator is notified of this fact by the operation of certain supervisory signals in her cord circuit. When the subscribers replace their receivers upon the switchhook after the 70 conversation is terminated each of the lines is completely disassociated from the cord circuit and may call or be called while the cord circuit is still associated with their local jack. If the operator desired to resignal 75 one of them by operating her ringing key she would again associate the desired party's line with the cord circuit.

In order to establish a main exchange connection the subscriber at substation A⁴ will 80 after connecting with a connector switch such as H² operate his calling device for the digit 0. By this operation the connector switch is raised to the tenth level after which it operates to automatically select an idle trunk 85 line extending to the main exchange. All trunk lines extending from the main to the branch exchange are two way trunk lines and so it will be one of these that is connected with by the calling subscriber at substation A⁴. In response to the remaining digits of the number of the subscriber in the 90 main exchange the connection is extended through the medium of the line switch C associated with the trunk line and the automatic switches in the main exchange, all 95 the foregoing operations taking place in a well known manner.

Had the main exchange been operating 100 manually when the two way trunk line was seized by the subscriber at substation A⁴ a line lamp would appear before a main exchange operator who would answer the call by inserting the plug of an idle cord circuit into the jack of the calling trunk line 105 and operate the listening key after which the call would have been extended to the desired local substation in the main exchange in the usual manner. When the conversation is terminated the calling subscriber at 110 substation A⁴ will release the operated switches in the usual manner by replacing his receiver upon the switchhook.

The attendant operator in the private automatic exchange is also provided with 115 means for calling into the main exchange. She may do this by throwing her calling out key and operating her calling device for the digits of the local subscriber's number or by inserting the calling end of an idle cord circuit 120 into the jack J² associated with the incoming trunk line and operate her calling device for these digits.

A subscriber in the isolated private branch exchange may also make a call in the private 125 automatic exchange by signalling the branch exchange operator and having her complete the connection by way of the individual line switch C⁷ associated with the two way trunk line extending to the private branch ex- 130

change and the automatic switches in the private automatic exchange.

A local connection between subscribers in the private branch exchange may be completed in the usual manner by way of an idle cord circuit such as the one indicated diagrammatically at Fig. 19.

Having described generally the various connections in the main, private automatic, and branch exchanges a detailed description of the circuits will now be given. For this purpose it will first be assumed that a subscriber in the main automatic exchange desires to establish a connection with the subscriber at substation A⁴ in the branch exchange and that he has operated a selector switch and a selector repeater E thereby extending his line into connection with an idle trunk line extending to the private automatic exchange, which we will assume, is the trunk line comprising conductors 51 and 52. Immediately upon the selector repeater E connecting with this trunk line ground is placed on the test contact 21 by means of the private wiper. A circuit is thus completed extending through the holding winding 2 of the line switch C. The holding winding upon energizing, attracts the cut off armature 6 thereby disconnecting the trunk line from its normal battery and ground connections in the line switch C. The trunk line comprising conductors 51 and 52 extends through the attendant's cabinet in the branch exchange (shown in Figs. 3 and 4), and terminates in dual switches H and H' (Figs. 5, 6, 7 and 8). In the selector repeater E a bridge is placed across the trunk line and the line relay 506 of the main selector H is energized over the line circuit through the selector repeater E in series with the impedance coil 513. Upon energizing the line relay 506 at armature 545 completes a circuit for the slow acting release relay 507. The latter relay upon energizing, prepares the operating circuits of the main connector H at armature 547 and at armature 548 places ground on release trunk conductor 444 thereby closing a circuit which extends by way of conductor 182, back contact and armature 124, armature 130 and its back contact, and thence through the winding of the cut off relay 103 to battery. Relay 103 upon energizing, at armature 135 places a busy potential on the multiplied release trunk conductor 971 which is accessible to the local switches and at armature 136 places the busy potential upon the pack J³ associated with the trunk line in the attendant's cabinet.

If the circuits in the attendant's cabinet are so arranged that the main exchange subscriber will be able to operate the dual connectors without restriction the key K¹⁷ will be operated. Under these conditions as soon as ground is placed on release trunk conductor 182 a circuit is completed extending

through the working contact of spring 210 of key K¹⁷ and the said spring, by way of back contact and armature 215 and thence through the busy lamp L⁷ to battery. By the operation of this signal the attendant operator will be notified that the trunk line is in use.

When the calling device at the calling substation is operated for the next digit of the desired branch exchange subscriber's number a series of interruptions are produced in the line relay of the selector repeater in the usual manner. These interruptions are repeated over the trunk line to the line relay 506 of the main connector H which relay deenergizes a plurality of times in response thereto. At each deenergization, a circuit is completed extending from ground by way of armature 545 and its back contact, conductors 443, conductor 290, spring 211 of key K¹⁷ and its working contact, conductor 285, conductor 442, armature 547 and its front contact, armature 571 and its back contact, back contact and armature 555, through the winding of the slow acting relay 508, through the winding of the vertical magnet 581 and thence to the switch wiper 577 in its first position to battery. Magnet 581 operates to raise the switch wipers 590-593, inclusive, step by step until they are placed opposite the level of bank contacts in which is located the contact set associated with the line of the desired private automatic exchange subscriber. The slow acting relay 508 is energized in series with the vertical magnet and at its armature 550 completes the circuit of the private magnet 582. The private magnet 582 is thus maintained energized throughout the vertical operation of the switch and at the termination thereof deenergizes, immediately following the deenergization of a slow acting relay 508, thereby allowing the side switch wipers to advance to their second position.

The calling subscriber may now operate his calling device in accordance with the last digit of the desired called subscriber's number. As before, a series of interruptions is produced in the circuit of the line relay of the selector repeater E and these are in turn repeated to the line relay 506 of the main connector H. The latter relay in response to the interruptions on its line circuit deenergizes a corresponding number of times. At each retraction of its armature 545 a circuit is completed extending from ground by way of the said armature and its back contact, conductor 443, conductor 290, spring 211 of key K¹⁷ and its working contact, conductor 285, conductor 442, armature 547 and its front contact, armature 571 and its back contact, back contact and armature 555, winding of slow acting relay 508, winding of the rotary magnet 580 and thence by way of side switch wipers in the second position to bat-

terry. The rotary magnet 580 operates to rotate the switch wipers 590-593, inclusive, into engagement with the contact set associated with the line of the desired subscriber which, we will assume, are the bank contacts 625-628, inclusive, associated with the line of the substation A⁴. If the line of the desired called subscriber is idle at this time the slow acting relay 508 will deenergize as will the private magnet 582 and side switch wipers will be advanced to their third and final position. However, it will be assumed that the desired subscriber's line was busy when connection thereto was attempted. Under these conditions there will be a ground potential present on the test contact 627 engaged by the test wiper 592. Then, immediately upon the switch wipers being rotated into engagement with this contact set, a circuit is completed extending from the said grounded test contact by way of the test wiper 592, side switch wiper 576 in the second position, normally closed springs controlled by armature 575, through the winding of the busy relay 510, normally closed springs controlled by armature 550, and thence through the winding of the private magnet 582 to battery. The busy relay 510 is energized over this circuit and the private magnet is also maintained energized. Relay 510 upon energizing establishes a locking circuit for itself at armature 575 and at armature 561 completes a circuit extending from ground by way of the front contact and armature 561, and through the winding of the relay 509 to battery. Upon energizing, relay 509 establishes a locking circuit for itself at armature 557 which circuit extends from ground on release-trunk conductor 444, armature 359 and its back contact, armature 347 and its back contact, conductor 187, back contact and armature 172, conductor 186, conductor 435, armature 557 and its front contact, and thence through the winding of the relay 509 to battery. Another result of the energization of relay 509 is that a circuit is completed for the release magnet 584 extending from ground by way of front contact and armature 556, working contact of off normal spring 600 and said spring, and thence through the winding of release magnet 584 to battery. By the operation of the relay 509 a busy tone is placed on the calling subscriber's line over the following circuit: From the busy machine by way of conductor 439, back contact and armature 542, armature 554 and its front contact, conductor 461, off normal spring 363 and its resting contact, conductor 460, back contact and armature 521, conductor 424, conductor 286, and thence over the trunk line to the calling subscriber. The release magnet 584 is energized over the previously traced circuit and operates to restore the connector H to its normal position.

The calling subscriber has now two courses open to him, one of these being that he may replace his receiver upon the switchhook thereby releasing the operated switches in a manner to be described hereinafter or he may operate his calling device in accordance with the digits of another branch exchange subscriber's number. The operation in the latter case will now be described.

When the calling device at the calling substation is operated in accordance with the digit of this local branch exchange subscriber's number a series of interruptions is produced in the circuit of the line relay of the selector repeater E and in the usual manner these are repeated to the line relay 506 of the main connector H, the latter relay deenergizing a corresponding number of times. At each retraction of its armature a circuit is completed extending from ground, by way of armature 545 and its back contact, conductor 443, conductor 290, spring 211 of key K¹⁷ and its working contact, conductor 285, conductor 442, armature 547 and its front contact, armature 552 and its back contact, conductor 459, armature 358 and its back contact, back contact and armature 344, winding of slow acting relay 308, through the winding of the vertical magnet 366 of the auxiliary connector H' and thence by way of the side switch wiper 470 in its first position to battery. The vertical magnet 366 of the auxiliary connector switch H' operates to raise the switch wipers 385-388, inclusive, step by step until they are placed opposite the level of bank contacts in which is located the terminals of the desired subscriber's line. The slow acting relay 308 is energized in series with the vertical magnet and in the usual manner operates the private magnet in order to advance the side switch wipers into their second position. Immediately upon the first vertical step of the switch shaft the off normal springs 363 are opened and the busy tone is removed from the calling subscriber's line.

When the calling device at the calling substation is operated in accordance with the last digit of the desired branch exchange subscriber's number a series of interruptions is produced in the circuit of the line relay 506 which deenergizes a corresponding number of times. At each retraction of its armature 545 a circuit is completed extending from ground by way of the said armature and its back contact, conductor 443, conductor 290, spring 211 of key K¹⁷ and its working contact, conductor 285, conductor 442, armature 547 and its front contact, armature 552 and its back contact, conductor 459, armature 358 and its back contact, back contact and armature 344, through the winding of the slow acting relay 308, through the winding of the rotary magnet 363, and through the side switch wiper 470 in its sec-

ond position to battery. The rotary magnet 365 operates to rotate the switch wipers of the auxiliary connector switch H' into engagement with the contact set associated with the desired subscriber's line which we will assume are the bank contacts 400-403, inclusive.

The further operation of the connector H' depends upon whether the desired line is 10 busy or idle. It will be assumed in the present case that the desired subscriber's line was idle at this time. Under these conditions, immediately following the termination of the rotary movement of the switch, the 15 slow acting relay 308 is deenergized and the private magnet deenergizes also, thereby causing the side switch wipers to advance to their third position. Immediately upon the 20 side switch wipers advancing to their third position a circuit is completed extending from ground by way of the side switch wiper 471, test wiper 387, test contact 402, conductor 672, conductor 639 and thence through the holding winding 702 of the line switch C' 25 to battery. The holding winding energizes over this circuit and operates to attract the cut off armature 705 thereby disconnecting the line conductors of the substation A' from their normal battery and ground connections 30 in the line switch C'. Another result caused by the advance of the side switch wipers to their third position is that a circuit is completed for the switching relay 312 in an obvious manner. Relay 312 upon energizing, 35 at armature 359 opens the previously traced locking circuit of the relay 509 in the main connector H and at armatures 355 and 361 completes the ringing circuit which circuit extends from generator V' by way of front 40 contact and armature 116, conductor 292, conductor 454, back contact and armature 354, armature 361 and its front contact, wiper 388, bank contact 403, and thence over the line of the substation A' through the 45 ringer and condenser of this substation, bank contact 400, wiper 385, front contact and armature 355, armature 351 and its back contact, and thence through the upper winding of ring cut off relay 311 to battery. It 50 is of course apparent that upon the first off normal step of either of the dual connectors H or H' the relay 117 is energized and the solenoid interrupter I' begins to operate thus intermittently opening and closing the circuit of the relay 115 which relay at its armature 116 intermittently applied ringing current to the above traced circuit.

When the called subscriber answers a path 60 for direct current is completed over his line loop and the ring cut off relay 311 is immediately energized. Relay 311 upon energizing, establishes a locking circuit for itself at armature 353 and at armatures 351 and 354 cuts off the ring and at the front contacts of 65 these armatures finally completes the talking

connection. The back bridge relay 302 supplies talking battery to the called subscriber at substation A' and is of course energized over his line loop. Upon energizing, relay 302 at armature 319 completes the circuit of the slow acting relay 303. The latter relay 70 upon energizing, at armature 324 prepares the operating circuit of the main connector H and at armature 321 places ground on the conductor 283 which extends the winding of the solenoid slow set 203 to battery. The 75 solenoid 203 immediately pulls up its plunger arm 220 thereby closing the circuit of the relays 201 and 204 in multiple. The operation of relay 204 when the key K¹⁷ is thrown 80 is without function. Relay 201 upon operating, reverses the battery over the calling subscriber's line loop for any desirable purpose. It will be understood that the solenoid 203 is made slow to fall back by any well known 85 mechanical arrangement such as a dashpot, so that the battery flow over the incoming trunk line will not be restored to normal until sometime after the called subscriber has hung up. This provision is made so that 90 a called subscriber may hang up in order to release the switch he has used to pass the call without restoring the normal battery flow over the incoming trunk line. Conversation may now be carried on between the 95 calling and called subscribers over the heavy talking conductors. When this is terminated the calling subscriber by replacing his receiver upon the switchhook will release the operated switches in a manner to be described later.

Should the calling subscriber have obtained a connection with the first party he called by way of the main dual connector and that party did not answer the calling 105 subscriber could by operating his calling device have operated the auxiliary connector in the same manner as was above described. The main connector would be released immediately upon the deenergization of the line 110 relay 506 over the following circuit: Ground by way of front contact and armature 387, conductor 468, armature 567 and its front contact, working contact of off normal 115 spring 597 and the said spring, and thence through the winding of relay 509 to battery. Relay 509, upon energizing, establishes a locking circuit for itself at armature 557 and at armature 556 completes the release magnet circuit. The main connector H is thus restored to normal and the auxiliary connector is operated into connection with the desired line. If this last party does not answer the 120 calling subscriber may again operate the main connector H as the locking circuit of the relay 509 is opened immediately upon the connector H' being brought into connection with a called line.

It will now be assumed that the calling subscriber at substation A desires to obtain 125

a connection with the subscriber at substation A⁵ and that he will therefore operate his calling device for the digits of the number assigned to this private automatic exchange subscriber. It will be assumed further that the calling subscriber operates his calling device for the first digit of the desired number before the called subscriber at substation A⁴ has replaced his receiver upon the switchhook. By this operation a series of interruptions is produced at the circuit of the line relay of the selector repeater E in the main exchange and these are repeated to the line relay 506 of the connector H. At each deenergization of the line relay 506 an impulse of current is sent over the following circuit: Ground by way of armature 545 and its back contact, conductor 443, conductor 290, spring 211 of key K¹⁷ and its working contact, conductor 285, conductor 442, armature 547 and its front contact, armature 571 and its back contact, back contact and armature 555, winding of slow acting relay 508, winding of the vertical magnet 581, and thence by way of side switch wiper 577 in its first position to battery. As before, the vertical magnet 581 operates to raise the switch wipers 590-593, inclusive, step by step until they are placed opposite the level of bank contacts in which is located the contact set associated with the substation A⁵. The slow acting relay 508 is energized in series with the vertical magnet and in the usual manner controls private magnet 582 in advancing the side switch wipers to their second position at the termination of the vertical movement of the switch.

At each deenergization of the line relay 506 another circuit is completed which extends from ground by way of armature 545 and its back contact, armature 546 and its front contact, conductor 447, and thence through the winding of the slow acting relay 307 to battery. Relay 307, upon energizing, initiates the release of the auxiliary connector H' by completing a circuit extending from ground by way of front contact and armature 338, armature 360 and its front contact, off normal spring 375 and its working contact, and thence through the winding of relay 309 to battery. Relay 309, upon energizing establishes a locking circuit for itself at armature 345 which extends from ground on release trunk conductor 444, armature 572 and its back contact, armature 562 and its back contact, conductor 462, armature 345 and its front contact, and thence through the winding of relay 309 to battery. Another result of the energization of relay 309 is that the circuit of the release magnet 367 is completed and the operative circuits of the auxiliary connector opened. The operation of magnet 367 releases the auxiliary connector switch and

consequently the subscriber at substation A⁴ is released from the connection.

When the calling device is operated for the last digit of the number of the desired substation in the private automatic exchange the line relay 506 is again operated and a series of impulses are sent over the following path: Ground by way of armature 545 and its back contact, conductor 443, conductor 290, spring 211 of key K¹⁷ and its working contact, conductor 285, conductor 442, armature 547 and its front contact, armature 571 and its back contact, back contact and armature 555, winding of slow acting relay 508, winding of the rotary magnet 580, and through the side switch wiper 577 in its second position to battery. The rotary magnet 580 operates in the usual manner to rotate the switch wipers into engagement with the contact set associated with the line of the substation A⁵ which we will assume are the bank contacts 620-623, inclusive. The slow acting relay 508 is energized in series with the rotary magnet and as before controls the operation of the private magnet 582 in advancing the side switch wipers to their third position.

Assuming that the line of the desired subscriber is idle at this time the side switch wipers will be advanced to the third position and a circuit will be completed extending from ground by way of side switch wiper 576, test wiper 592, bank contact 622, conductor 643 and thence through the holding winding of the line switch C⁵ to battery. The line switch C⁵ is only indicated diagrammatically but it will be apparent that this line switch is similar to the line switch C⁴. Substation A⁵ is also indicated only diagrammatically but is of the usual automatic type being identical with the substation A⁴.

It may happen that the called subscriber at substation A⁵ was engaged in important business at this time and that he did not desire to be annoyed by outside calls. Under these conditions he will restore the key at his substation similar to the key K²² at substation A⁴ to normal. By this operation the conductor 642 is grounded as becomes the multiple bank contacts 621 and similar contacts in the banks of the dual connector switches.

Returning now to the operation of the connector H when the side switch wipers were advanced to their third position, it will be apparent that the switching relay 512 is energized over a circuit extending from ground, by way of side switch wiper 576, winding of the switching relay 512, and through the side switch wiper 577 in its third position to battery. Upon energizing, relay 512 opens the locking circuit of the relay 309 in the auxiliary connector at arma-

ture 572; and at armature 568 completes a circuit extending over the following path: From the grounded contact 621 by way of wiper 591, front contact and armature 568, 5 lower winding of the slow acting relay 505, conductor 438, conductor 188, armature 173 and its back contact, conductor 189, back contact and armature 230, conductor 189', conductor 426, armature 535 and its back 10 contact, conductor 431, back contact and armature 320, conductor 433, working contact of off normal spring 597 and the said spring, and thence through the winding of the relay 509 to battery. Relays 505 and 15 509 are energized over this circuit. Relay 505 upon energizing, establishes a locking circuit for itself at armature 543 extending from ground on release trunk conductor 444, by way of armature 359 and its back 20 contact, armature 347 and its back contact, conductor 187, back contact and armature 172, conductor 186, conductor 435, armature 543 and its front contact, and thence through the upper winding of relay 505 to battery. 25 A branch of this locking circuit also extends by way of front contact and armature 541, conductor 441, conductor 280, and thence through the bar lamp L^e to battery. By the lighting of this lamp the attendant operator is notified that the line called by the 30 calling subscriber is barred. Relay 509 upon operating, establishes a locking circuit for itself at armature 557, and at armature 556 completes the circuit of the release magnet 35 584. Another result of the energization of relay 509 is that the operating circuits of the main connector H are opened at armature 555. It will be noted that the circuit over which the relay 509 is locked is the 40 same as that over which the relay 505 was maintained energized. A distinctive tone is now placed on the calling subscriber's line over a circuit which extends from the bar tone machine, front contact and armature 45 542, armature 554 and its front contact, conductor 461, off normal spring 363 and its resting contact, conductor 460, back contact and armature 521, conductor 286, and thence to the calling substation. This tone will inform 50 the calling subscriber that the line he desires is inaccessible to him at the present time and he will replace his receiver upon the switchhook thereby releasing the operated switches in a manner to be described 55 hereinafter.

It will now be assumed that the line of the subscriber at substation A⁵ was not barred and the calling subscriber attempted to connect therewith. Under these conditions there will be no ground present on the bank contact 621 and no circuit will be completed for the relays 505 and 509. Then immediately upon the energization of relay 512 the ringing current is intermit- 60 tently applied to the line of the called substation until an answer is obtained. When this occurs there will be a circuit completed over the called subscriber's line loop for ring cut off relay 511. Upon energizing, relay 511 establishes a locking circuit for itself at 65 armature 565 and at armatures 563 and 566 cuts off the ring and at the front contacts of these armatures finally completes the talking connection. Talking battery is supplied to the calling subscriber through the winding of the line relay 506 and the winding of the impedance coil 513 and to the called subscriber through the windings of the back bridge relay 501. Relay 501 is of course 70 energized over the line of the called subscriber and, upon operating, completes a circuit at its armature 523 for the slow acting relay 502. Relay 502 upon energizing, 75 places ground on the conductor 283 thereby completing the circuit of the solenoid slow set 203 and at armature 526 prepares the operating circuits of the auxiliary connector H'. The plunger arm of the solenoid 203 is immediately attracted and the circuit of the reversing relay 201 is completed. The 80 latter relay operates in the usual manner to reverse the battery over the calling subscriber's line loop for supervision or for any other desirable purpose.

During the conversation between the calling and called subscribers at substations A and A⁵ the called subscriber may find it desirable to call another party in the branch exchange. In order to do this the subscriber at substation A⁵ will operate his calling device in accordance with the first digit of the desired local branch exchange subscriber's number. By this operation a series of interruptions is produced in the circuit of the back bridge relay 501 which relay retracts its armatures a corresponding number of times. At each retraction of its armature 523 a circuit is completed extending from ground by way of the said armature and its back contact, armature 526 and its front contact, armature 552 and its back contact, conductor 459, armature 358 and its back contact, back contact and armature 344, winding of the series relay 308, winding of the vertical magnet 366, and thence by way of the side switch wiper 470 in its first position to battery. The vertical magnet 366 operates in the usual manner to raise the switch wipers 385-388, inclusive, step by step until they are placed opposite the level of bank contacts in which is located the line of the desired substation. The slow acting relay 308 is energized in series with the vertical magnet and, as before described, controls the operation of the private magnet 368 in advancing the side switch wipers to their second position following the termination of the vertical movement of the switch.

The called subscriber at substation A⁵ may now operate his calling device for the final digit of the desired called subscriber's number. As before back bridge relay 501 50 tracts its armature a plurality of times in response to the interruptions in its line circuit. At each deenergization, a circuit may be traced extending from ground by way of armature 523 and its back contact, armature 526 and its front contact, armature 552 and its back contact, conductor 459, armature 358 and its back contact, back contact and armature 344, winding of the slow acting series relay 308, winding of the rotary magnet 365, and through the side switch wiper 470 in its second position to battery. The rotary magnet 365 operates in the usual manner to rotate the switch wipers into engagement with the bank contacts associated 20 with the line of the desired substation which we will assume are bank contacts 400-402, inclusive, associated with the line of the substation A⁴. At each deenergization of the back bridge relay a circuit is completed for 25 the slow acting relays 500 and 503 in multiple with the above traced operating circuits. The operation of relay 503 is without function at this time. Relay 500 upon energizing, opens the inductive connection to the 30 calling subscriber's line thereby preventing him from receiving any dial interruptions in his receiver. The slow acting relay 308 is energized in series with the rotary magnet and controls the operation of the private 35 magnet 368 whereby if the desired line is idle the side switch wipers are advanced to their third position.

Should the desired line be busy at this time there will be a ground potential present 40 on the test contact 402 engaged by the test wiper 387. A circuit is then completed extending from the said grounded test contact by way of the test wiper 387, side switch wiper 471, in its second position, normally closed springs controlled by armature 349, winding of the busy relay 310, normally closed springs controlled by armature 339, and thence through the winding of private magnet 368 to battery. The busy relay 310 is energized over this circuit and the private magnet is prevented from deenergizing 45 and allowing the side switch wipers to advance to their third position. Upon energizing, relay 310 establishes a locking circuit for itself through the working contact of off normal spring 377 and the said spring at armature 349, and at armature 348 completes a circuit extending from ground by way of front contact and armature 348, and 50 thence through the winding of the relay 309 to battery. Relay 309, upon energizing, establishes a locking circuit for itself at armature 345 which extends from ground by way of armature 522 and its front contact, armature 532 and its back contact, conductor 462,

armature 345 and its front contact, and thence through the winding of relay 309 to battery. Relay 309, upon operating, also completes a circuit at armature 346 for the release magnet 367. A busy tone is now 70 given to the calling and called subscribers over a circuit which extends from the busy machine by way of back contact and armature 333, front contact and armature 342, conductor 450, armature 529 and its front 75 contact, conductor 451, and thence to the lower talking conductor of the auxiliary dual connector H'. It will be apparent that this tone is audible to both the calling and first called subscribers. 80

If the called subscriber at substation A⁵ desires to call another party in the private automatic exchange three courses remain open to him the first of which is, he may replace his receiver upon the switchhook, 85 then remove it again and operate his calling device for the digits associated with the number of the next party desired, or he may prefix 1 to the desired called subscriber's number or dial the digits of the called subscriber's number without hanging up his receiver. 90

The first of these cases will now be described. When the receiver is replaced at substation A⁵ the circuit of the back bridge 95 relay 501 is opened and upon its deenergization, the locking circuit of the relay 309 is broken at the front contact of armature 522. This relay immediately deenergizes and at armature 344 prepares the operating circuits of the auxiliary connector. It will be noted that when the receiver is replaced at substation A⁵ an impulse of current is sent over the following path: Ground by way of armature 523 and its back contact, armature 526 and its front contact, armature 552 and its back contact, conductor 459, armature 358 and its back contact, back contact and armature 344, winding of the slow acting relay 308, winding of the vertical magnet 366, and thence by way of the side switch wiper 470 in its first position to battery. The vertical magnet 366 operates in response to this impulse to raise the switch shaft one step. On the shaft 483 is a projection 481 105 which is adapted to operate the springs 480-482, inclusive, upon the first step of the switch. Following the termination of this impulse of current the vertical magnet is deenergized as is the slow acting relay 308 110 which energized in series with it. A circuit is then completed extending from ground by way of armature 340 and its back contact, spring 482, spring 481, off normal spring 378, and its working contact, and thence through the winding of the release magnet 367 to battery. Magnet 367 operates in the usual manner to restore the auxiliary connector H' to normal. Thus this impulse of current has no effect as the auxiliary con- 115 120 125 130

necter is immediately released upon being operated to the first level.

When the receiver is removed at substation A⁵ the circuit of the back bridge relay 501 is again completed. The called subscriber by operating his calling device may now control the operation of the auxiliary connector H in the same manner as hereinbefore described to complete a connection to the desired called subscriber's line.

If the called subscriber had prefixed 1 to the desired party's number instead of hanging up it will be apparent that the back bridge relay would be deenergized and 15 would open the locking circuit of the relay 309 which relay would deenergize to prepare the operating circuits of the auxiliary connector. As before an impulse of current 20 would be sent to the vertical magnet 366 but the auxiliary switch would be immediately released.

Had the calling subscriber at substation A⁵ operated his calling device in accordance with the digits of the next desired subscriber's number without prefixing the digit 25 1 or replacing his receiver upon the switchhook the auxiliary switch would be operated in the usual manner. It will be seen that upon the first interruption produced by the 30 calling device back bridge relay 501 deenergizes and the locking circuit of the relay 309 is opened. The latter relay upon deenergizing, removes the busy tone from the line and at the same time prepares the 35 operating circuits of the connector H'. Thus the auxiliary connector H will be operated in a manner hereinbefore described to make connection with the desired subscriber's line.

It will now be assumed that the line of 40 the substation A⁴ was idle when connection was attempted therewith by the auxiliary connector H'. Under these conditions there will be no ground potential present on the test contact 402 engaged by the test wiper 45 387 and no circuit will be completed for the busy relay 310 and the private magnet will consequently deenergize advancing the side switch wipers into their third position. Immediately upon the side switch wipers being advanced to their third position a circuit is completed for the holding winding 702 of the line switch C⁴. The holding winding 50 705 upon energizing attracts the cut off armature thereby disconnecting the line of this 55 substation from its normal battery and ground connections in the line switch C⁴.

When the side switch wipers 470-471 are advanced to their third position a circuit is completed for the switching relay 312. Relay 60 312 upon energizing, at armatures 355 and 361 completes the ringing circuit. Ringing current is then intermittently applied to the line of the called substation A⁴ until the subscriber thereat removes his receiver from the switchhook.

When the receiver is removed at substation A⁴ ring cut off relay 311 will be energized. Upon operating, this relay at armature 353 completes a locking circuit for itself. A branch of this locking circuit extends by 70 way of conductor 452 through the winding of the relay 504 to battery. Relay 311 upon operating also extends the called subscriber's line to the windings of the back bridge relay. Relay 504 upon energizing, reverses 75 the battery supplied by the back bridge relay 501 over the line of the called subscriber at substation A⁵ whereby the subscriber thereat is notified of the response of the second called party. The back bridge relay 302 80 of the auxiliary connector H' is of course energized over the line loop of the subscriber at substation A⁴, and upon operating, closes the circuit of the slow acting relay 303. The latter relay operates in the same manner as 85 before to ground the conductor 283 extending to the solenoid slow set which controls the supervision to the calling subscriber and prepare the operating circuit for the main connector H.

While the first called subscriber at substation A⁵ is passing the call provision must be made to enable him to release the auxiliary connector H' under certain conditions, such as when he operates his calling device 90 for a wrong number or the called subscriber does not answer. Provision must be made also so that the first called party is enabled to hang up before the second called party answers without releasing the connection of 100 the calling subscriber to this last called subscriber's line. The various release circuits over which these results are accomplished will now be described.

The first of these conditions will now be 105 described. For this purpose it will now be assumed that the subscriber at substation A⁵ has operated the auxiliary switch H' for a digit of the called subscriber's number and makes a mistake in operating his calling device. In order to restore the auxiliary connector H' he will merely replace his receiver upon the switchhook thereby opening the circuit of the back bridge relay 501. The latter relay upon deenergizing, opens the 110 circuit of the slow acting relay 502. During the interval following the deenergization of the back bridge relay 501 and the deenergization of the slow acting relay 502 an impulse of current is sent to the slow acting 115 relay 503.

Upon the deenergization of the slow acting relay 502 a circuit is completed extending from ground by way of armature 527 and its back contact, armature 533 and its front contact, conductor 434, armature 357 and its back contact, off normal spring 375 and its working contact, and thence through the winding of the relay 309 to battery. Relay 309 operates in the same manner as before to close 120 125 the circuit of the slow acting relay 502.

the circuit of the release magnet 367 of the auxiliary connector H'. However, it does not complete a locking circuit for itself as the main connector H is in an operated position and the relay 512 is operated. The release magnet 367 operates to restore the auxiliary connector to normal. When the called subscriber at substation A⁵ removes his receiver from the switchhook and operates his calling device for the digits of the desired subscriber's number the auxiliary connector H' will be again operated in the usual manner.

It will now be assumed that the desired called subscriber does not answer and the first called subscriber desires to call another private automatic exchange party. In order to release the connector H he will operate his calling device for the digit 1. By this operation an interruption is produced in the circuit of the back bridge relay 501 and an impulse of current is sent to the slow acting relay 503. A circuit may now be traced extending from ground by way of armature 522 and its front contact, front contact and armature 532, conductor 446, armature 360 and its front contact, off normal spring 375 and its working contact, and thence through the winding of relay 309 to battery. Relay 309 will operate in the same manner as in the preceding explanation and the auxiliary connector H' will be accordingly released. By operating his calling device for the digits of the number associated with the next party desired the subscriber at substation A⁵ will be able to again reoperate the connector H'.

Should the called subscriber at substation A⁵ hang up his receiver after the connector H' establishes a connection with the called subscriber's line the back bridge relay 501 is deenergized and an impulse of current is sent to the slow acting relay 503 and the circuit of the slow acting relay 502 is broken. A circuit is now completed extending from ground by way of armature 527 and its back contact, armature 533 and its front contact, conductor 434, armature 357 and its front contact, conductor 433, working contact of off normal spring 597 and the said spring, and thence through the winding of relay 509 to battery. Relay 509 upon energizing, completes the circuit of the release magnet 584 of the main connector H at armature 556 and the main connector H is accordingly restored to normal.

Returning now to the operation of the dual switches when both the called subscribers at substations A⁴ and A⁵ are in connection with each other it will be seen that a conference may be held between the three subscribers. After this is terminated either one of the called parties upon replacing his receiver upon the switchhook will release the connector switch which has

been operated in connection with his line. It will be assumed that the subscriber at substation A⁵ replaces his receiver. By this operation the main connector H is released in the same manner as was described hereinbefore. Immediately upon the connector restoring to normal the ring cut off relay 511 deenergizes and the circuit of the reversing relay 305 is opened. Upon deenergizing, this relay restores the normal connections of battery to the line of the called subscriber at substation A⁴. Had the called subscriber at substation A⁴ been the one to replace his receiver auxiliary connector H' would have been released, and the reversing relay 504 in the main connector H would have been deenergized.

However, it will be assumed that during the conference the subscriber at substation A⁵ desires to dismiss the subscriber at substation A⁴. In order to do this he will operate his calling device for the digit 1. By this operation one interruption is produced in the circuit of the back bridge relay 501 and a current impulse is sent to the slow acting relay 503. A circuit is now effective extending from ground by way of armature 522 and its front contact, armature 532 and its front contact, conductor 446, armature 360 and its front contact, off normal spring 375 and its working contact, and thence through the winding of the relay 309 to battery. Relay 309 energizes over this circuit, and operates in the same manner as before to initiate the release of the auxiliary connector H'.

It will be apparent that the subscriber at substation A⁴ could in a manner similar to that above, described dismiss the subscriber at substation A⁵ from the connection if so desired, by operating his calling device for the digit 1. By this operation an interruption would have been produced in the circuit of back bridge relay 302 of the auxiliary connector H' and an impulse of current would have been sent to the slow acting relay 304. A circuit is now effective extending from ground by way of armature 318 and its front contact, armature 329 and its front contact, conductor 468, armature 567 and its front contact, working contact of off normal spring 597 and said spring, and thence through the winding of the relay 509 to battery. Relay 509, upon energizing, establishes a locking circuit for itself and completes the circuit of the release magnet 584 of the main connector H. By the energization of the magnet the main connector H is restored to normal.

It will be noted that any called subscriber may transfer the call to a barred substation as the circuit of the relays 505 and 305 are opened at the contacts of the slow acting relays controlled by the back bridge relays of either connector switch. This will be

clear from the following brief description. It will be assumed in this case that the called subscriber at substation A⁵ desired to transfer the call to the subscriber at substation A⁴ whose line at that time was barred. The calling device at substation A⁵ would be operated in accordance with the digits of the number assigned to the substation A⁴ and the wipers of the auxiliary connector H' would be operated in response to the digits of this number into connection with the line of the desired substation A⁴. The switching relay 312 will be energized as before as will the holding winding 15 of the line switch C⁴. A ground potential will be present on the bank contact 401 engaged by the wiper 386. However, this circuit is opened at armature 530 of the main connector H and consequently this ground 20 has no effect.

In the dual switches it is possible to bar certain groups of lines from outside service. The manner in which this result is accomplished will be described in connection with the connector H'. In order to bar certain groups of these lines a cam 417 is mounted on the switch shaft so as to operate the spring 419 when the switch wipers engage the bank contacts associated with any one 25 of the barred groups of lines. It will now be assumed that a calling subscriber has operated the auxiliary connector switch H' into engagement with the terminal of a line in one of the barred groups and upon the side switch wipers advancing to their third position the switching relay 312 is energized, the bank contacts with which the switch wipers are associated being a barred group, the spring 419 will be in engagement with 30 its front contact and a circuit is thereupon completed extending from ground by way of spring 419 and its working contact, front contact and armature 356, lower winding of the slow acting relay 306, armature 325 and its back contact, conductor 427, back contact and armature 530, conductor 428, and thence through the winding of relay 309 to battery. Relays 306 and 309 are energized 35 over this circuit. Relay 306 upon energizing, establishes a locking circuit for itself at armature 335 and at armature 334 lights the bar lamp L⁶ before the attendant operator. Relay 309 upon energizing, establishes a locking circuit for itself at armature 345 and 40 at armature 348 closes a circuit of the release magnet 367 whereby the auxiliary connector switch is restored to normal. The release lamp L⁶ is of course lighted its circuit being in multiple with that of the relay 309. 45 A distinctive bar tone is now given to the calling subscriber over a circuit which was described hereinbefore. In this manner it is possible to bar various groups of lines. These lines may be located in one level and 50 the whole level barred or only part of the

level barred. This is accomplished by having the cam 417 mounted eccentrically on the shaft.

Returning now to the operation of the dual connectors H and H' when the called subscriber at substation A⁵ releases the subscriber at substation A⁴ should the calling subscriber desire a connection with a subscriber in the branch exchange whose line is not accessible to the dual connectors the 70 called subscriber at substation A⁵ is enabled to signal the attendant operator. In order to do this he will operate his calling device for the digit 0. By this operation ten interruptions are produced in the circuit of the 75 back bridge relay 501. At each retraction of its armature 523 an impulse of current is sent to the vertical magnet 366 of the auxiliary connector H' in series with the slow acting relay 308. The vertical magnet 80 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

366 operates to raise the switch shaft ten steps. The slow acting relay 308 is energized in series with the vertical magnet and controls the private magnet 368 in the usual manner in controlling the operation 90 of the side switch wipers. When the switch shaft is raised to the tenth level the projection 484 thereon is adapted to operate the springs 420-422, inclusive, into engagement. Following the termination of the vertical movement of the connector H' the slow acting relay 308 is deenergized and a circuit is completed which extends from ground by way of armature 340 and its back contact, spring 420, spring 421, working contact of off normal spring 378 and the said spring, and thence through the winding of release magnet 367 to battery. Magnet 367 operates in the usual manner to restore the auxiliary connector switch to its normal position. Another circuit completed in multiple with the above extends from ground by way of armature 340 and its back contact, spring 422, conductor 470, front contact and armature 535, conductor 457, and thence through the winding of relay 314 to battery. Relay 314 is energized over this circuit and, upon operating, establishes a locking circuit for itself at armature 575 which extends from ground on release trunk conductor 182, spring 250 of key K¹² and its resting contact, spring 259 of key K¹⁶ and its resting contact, conductor 294, conductor 463, armature 575 and its front contact, and thence through the winding of relay 314 to battery. Relay 314 upon energizing, also completes a circuit which extends from ground by way of front contact and armature 579, conductor 279, and thence through the calling lamp L¹⁰ to battery. The operation of this lamp serves to signal the attendant and she will operate either one of her listening keys K¹² or K¹⁶ in order to ascertain what number is required. Assuming that the key K¹² is operated, when this occurs

curs the previous traced locking circuit of the relay 314 is broken and this relay de-energizes thereby extinguishing the calling lamp L^{10} . Another result of the operation 5 of key K^{12} is that the operator's head set is associated with the trunk line and the answering lamp L^9 lighted. Assuming now that the operator finds out the desired subscriber is the one located at the substation 10 A^8 (Fig. 11) and whose line terminates in jack J^{16} . The operator will restore the key K^{12} to normal, and operate the key K^8 , after which she will test the line of the called sub- 15 station with the tip of the plug P^2 in order to ascertain whether or not the line is idle and if so she will insert the plug P^2 into the jack J^{16} and operate the key K^{10} . Since the plug P^2 is moved from its normal position 20 the plug seat switch P. S. is operated. By this operation a circuit is completed extending from ground on release trunk conductor 182, working contact of spring 177 of key K^{10} and the said spring, back contact and armature 162, and thence through the wind- 25 ing of relay 104 to battery. Relay 104, upon energizing, completes the circuit of the relay 106 at armatures 140 and 142. Relay 106, upon energizing, completes a circuit extending from ground by way of front contact and 30 armature 149, armature 160 and its back contact, sleeve of plug P^2 , sleeve of jack J^{16} , and thence through the holding winding 926 of the line switch C^8 . Upon energizing, the holding winding attracts the cut off 35 armature 928 thereby removing the normal battery and ground connections from the line of the substation A^8 in the line switch C^8 . Another result of the energization of relay 106 is that the circuit of the relay 108 40 is completed. This relay, upon energizing, completes the ringing circuit which extends from the generator V by way of front contact and armature 113, back contact and armature 155, armature 158 and its front 45 contact, armature 163 and its back contact, resting contact of spring 128 and said spring, ring of plug P^2 , ring of jack J^{16} , thence through the condenser and ringer of the 50 substation A^8 , tip of jack J^{16} , tip of plug P^2 , spring 134 of key K^9 and its resting contact, back contact and armature 159, front contact and armature 157, armature 152 and its back contact, and thence through the 55 upper winding of the ring cut off relay 107 to battery. Ringing current is accordingly projected out over the above traced circuit until the subscriber at substation A^8 answers. When this occurs the circuit for the 60 direct current is completed over the called subscriber's line loop and the ring cut off relay 107 is energized. Relay 107 upon energizing, establishes a locking circuit for itself at armature 153 and at armatures 152 and 155 completes the talking connections. 65 Prior to this time the operator may restore

the listening key K^8 and need pay no further attention to the connection. Conversation may now be carried on over the heavy talking conductors between the calling subscriber in the main exchange, the called 70 subscriber at substation A^5 , and the called subscriber at substation A^8 . Battery is supplied to the called subscriber at substation A^8 from the windings of the back bridge relay 110. Relay 110 is of course energized 75 over the called subscriber's line loop and upon operating completes the circuit of the associated slow acting relay 111.

When the conversation is completed between the subscribers the subscriber at substation A^8 may replace his receiver upon the switchhook provided he desires no further connection. When the receiver is replaced at substation A^8 the back bridge relay 110 is deenergized and an impulse of current 80 is sent to the slow acting relay 112 at armature 166 at the same time an impulse of current is sent over the following circuit: From ground by way of armature 165 and its back contact, armature 170 and its front contact, 85 conductor 185, conductor 430, armature 552 and its back contact, conductor 459, armature 358 and its back contact, back contact and armature 344, winding of slow acting series relay 308, winding of the vertical 90 magnet 366 and thence through the side switch wiper 470 in its first position to battery. The vertical magnet 366 operates to raise the switch shaft one step. By this 95 operation the springs 480-482, inclusive, are operated and the connector switch H' is released so that this circuit is not effective at the present time. The circuit of the slow acting relay 111 being opened by the deenergization of the back bridge relay 110 this 100 relay deenergizes. A circuit may then be traced extending from ground by way of armature 169 and its back contact, armature 175 and its front contact, conductor 183, conductor 465, armature 569 and its front 105 contact, conductor 456, conductor 181, working contact of spring 167 and the said spring, where the circuit divides one path extending through the winding of the relay 109 to battery and the other to the lamp L^3 . Relay 109 upon energizing, establishes 110 a locking circuit for itself at armature 161 which extends from ground on release trunk conductor 182, working contact of spring 178 and the said spring, working contact of spring 179 on the plug seat switch P. S. and the said spring, front contact and armature 161, and thence through the winding of the relay 109 to battery. Another result of the energization of relay 109 is that 115 the plug P^2 is completely disassociated from the trunk line at armatures 159, 160 and 163 and consequently the holding winding of the line switch C^8 deenergizes. By the 120 latter operation the line of the substation 125

A^s is freed and the subscriber thereat may call or be called even though the plug P^2 remains in the jack J^{16} . Relay 109 upon operating, also opens the circuit of the relay 106, and that of relay 107. The operation of the lamp L^s serves to notify the attendant operator that the called subscriber at substation A^s has replaced his receiver upon the switchhook and she may withdraw the plug P^2 from the jack J^{16} and restore the key K^{10} to normal. When the plug P^2 assumes its normal position the locking circuit of the relay 109 is broken and the relay equipment associated with the plug P^2 is thereby restored to its normal position.

Should the subscriber at substation A^s desire to recall the subscriber at substation A^s he will signal the operator in the same manner as before and make this request. If the operator has not removed the plug P^2 from the jack J^{16} she will merely throw the listening key K^s in order to ascertain whether or not the called substation is busy. By the operation of this key the operator's head set is associated with the plug P^2 . If the desired line is idle the operator will operate her ringing key K^s thereby opening the locking circuit of the relay 109 and signalling the called subscriber. Relay 109, of course upon deenergizing, connects the plug P^2 with the incoming trunk line. The subsequent operations will take place in the same manner as hereinbefore described. It will be understood, of course, that the head set shown in Fig. 3 is the same one as that shown in Fig. 4 and both have been shown merely to simplify the drawings.

Returning now to the operation of the system when the subscriber at substation A^s has responded he may find it desirable after communicating with the subscriber at substation A^s to dismiss the latter party from the connection. In order to do this the last called party will operate his calling device for the digit 1. By this operation an interruption is produced in the circuit of the back bridge relay 110. This relay upon deenergizing sends a current impulse to the relay 112. A circuit may now be traced extending from ground by way of armature 169 and its front contact, armature 176 and its front contact, conductor 184, conductor 184', armature 570 and its front contact, working contact of off normal spring 600 and the said spring, and thence through the winding of the release magnet 584 to battery. Magnet 584 operates in the usual manner to restore the main connector H to normal and the subscriber at substation A^s is accordingly dismissed from the conversation.

Under certain conditions the subscriber at substation A^s may have found it desirable to dismiss the subscriber at substation A^s from the connection. In order to do this the subscriber at substation A^s will operate his calling device for the digit 1. By this operation an interruption is produced in the circuit of the back bridge relay 501 and an impulse of current is sent to the slow acting relay 503 which is thereby energized. A circuit may now be traced extending from ground by way of armature 522 and its front contact, armature 531 and its front contact, armature 569 and its front contact, conductor 456, conductor 181, working contact of plug seat spring 167 and the said spring, where the circuit divides one path extending through the winding of relay 109 to battery and the other path extending through the lamp L^s to battery. Relay 109 upon energizing, establishes a locking circuit for itself at armature 161 and at armatures 159, 160 and 163 disassociates the plug P^2 from the incoming trunk line. The subscriber at substation A^s is thereby released from the connection and his line is rendered free to either call or be called. Another result of the energization of relay 109 is that the circuit of relay 104 is opened. The latter relay upon deenergizing opens the circuit of the relay 106 and also the locking circuit of the ring cut off relay 107. This relay is thus deenergized. By the operation of the lamp signal L^s the attendant operator is notified that the party called by means of the plug P^2 has been released and she may accordingly withdraw the plug from its associated jack.

Returning now to the operation of the connection when the subscriber at substation A^s had released the subscriber at substation A^s , it will be assumed that this subscriber desires to call another party in the branch exchange for the calling subscriber. In order to do this the subscriber at substation A^s will operate his calling device in accordance with the digits of this local subscriber's number. A series of interruptions is thus produced in the circuit of the back bridge relay 110 associated with the plug P^2 . At each deenergization of this relay, an impulse of current is sent over the following circuit: Ground by way of armature 165 and its back contact, armature 170 and its front contact, conductor 185, conductor 430, armature 571 and its back contact, back contact and armature 555, winding of the series relay 508, through the winding of the vertical magnet 581 and thence by way of side switch wiper 577 in its first position to battery. The vertical magnet 581 operates to raise the switch wipers 590-593, inclusive, step by step until they are placed opposite the level of bank contacts in which is located the contact set associated with the desired subscriber's line. Slow acting relay 508 energized in series with the vertical magnet

2 and in the usual manner controls the operation of the private magnet 582 in stepping side switch wipers into their second position.

3 The subscriber at substation A⁸ may now 5 operate his calling device in accordance with 6 the next digit of the called subscriber's number. As before, back bridge relay 110 is de- 7 energized a corresponding number of times each time sending an impulse of current 10 over the previously traced impulsing circuit. However, these impulses are now effective to 15 operate the rotary magnet the side switch wiper 577 being in its second position. The 20 rotary magnet 580 operates in the usual manner to advance the switch wipers into engagement with the bank contacts in which 25 is terminated the line of the desired subscriber which we will assume are the bank contacts 625-628, inclusive, associated with 30 the line of the substation A⁴. The slow 35 acting relay 508 is of course energized in series with the rotary magnet and operates to control the advance of the side switch wipers to their third position provided the 40 line of the called subscriber is idle.

4 It will first be assumed, however, that the 45 line of the called substation was busy at this time. Under these conditions there will be a ground potential present upon the test contact engaged by the test wiper 592, the 50 private magnet will not deenergize, the connector H will be accordingly released, and the busy tone will be given to the calling subscriber in the main exchange and to the 55 subscriber at substation A⁸. It will be noted that the locking circuit of the relay 509 extends from ground by way of armature 166 and its front contact, conductor 191, resting contact of off normal spring 379 and the 60 said spring, conductor 455, armature 560 and its back contact, armature 559 and its front contact, and thence through the winding of the relay 509 to battery. This circuit enables the subscriber at substation A⁸ to remove the busy tone by going through the 65 same procedure as if he were called by means of one of the dual connectors. That is, he may either hang up his receiver and call another number, or prefix 1, or immediately proceed to dial the digits of the next 70 subscriber's number desired provided of course it is necessary to call another subscriber in the private automatic exchange. Any of these three operations produces an 75 interruption in the circuit of the back bridge relay 110 which accordingly deenergizes thereby opening the locking circuit of the 80 relay 509 which also deenergizes closing the operating circuits of the main connector H.

85 66 The call may now be passed in the same manner as was described hereinbefore.

90 It will now be assumed that the line of the desired substation was idle at this time. Following the deenergization of slow act- 95 ing relay 508 the side switch wipers will

100 be advanced to their third position and the circuit of the switching relay 512 completed. Ringing current will be then intermittently projected over the line of the substation A⁴ until an answer is obtained. When the 105 called subscriber answers the ring cut off relay 511 will be energized and the circuit of the back bridge relay 501 completed. The above operations have been described 110 fully hereinbefore and will be readily understood.

115 When the conversation is terminated the calling and called subscribers will replace their receivers upon the switchhook. When the receiver is replaced at the called substation the back bridge relay 501 will deenergize and an impulse of current may be sent to the vertical magnet of the auxiliary connector H'. This switch will of course be 120 stepped to the first level but will immediately release in the same manner as described before. When the calling subscriber in the main exchange replaces his receiver upon the switchhook the circuit of the line 125 relay of the selector repeater in the main exchange is opened and the bridge across the incoming trunk line in the main exchange is broken. By this last operation the line relay 506 of the main connector H is deenergized and the circuit of the slow 130 acting release relay 507 opened. Upon the deenergization of the slow acting relay 507, a circuit may be traced extending from ground by way of armature 548 and its back contact, working contact of off normal spring 597 and the said spring, and thence through the winding of the release relay 509 to battery. Relay 509 upon energizing, completes the circuit of the release magnet 584 in the usual manner. Upon ground being removed from release trunk conductor 444 by the deenergization of the slow acting release relay 507 the locking 135 circuits of the various operated relays are 140 opened and all apparatus in the exchange 145 is restored to normal.

150 The concern owning and operating the private automatic exchange shown in the drawings may find it desirable to limit the 155 passing of a call by the calling subscriber so as to prevent the indiscriminate calling of one private automatic exchange party after another and thus needlessly holding the incoming trunk lines busy. To this end the operator is provided with certain keys 160 which she may operate in order to restrict this passing of the call. If the key K¹⁷ is operated, key K¹⁷ being of course normal under these conditions, and the key K¹⁸ being left normal the calling subscriber is 165 only allowed to operate the dual connectors until connection is made with a line though he can of course pass the call, should the first lines he calls be busy. The called subscriber upon answering can, however, pass 170

the call to as many subscribers as he desires in the usual manner.

Should the key K^{18} be operated the calling subscriber is allowed to pass the call until 5 a called subscriber answers.

The first of these connections will now be described. For this purpose it will be assumed that the subscriber in the main exchange has seized the incoming trunk 10 line comprising conductors 50 and 51 by means of the selector repeater E in the main exchange. When this occurs a circuit will be completed for the line relay 506 of the main connector H. This relay upon operating 15 closes the circuit of the slow acting release relay 507 which operates to place ground on the release trunk conductors 444 and 182. Immediately upon ground being placed upon the release trunk conductor 182 20 a circuit is completed extending from the said grounded conductor by way of working contact of spring 210 of key K^{17} and the said spring, back contact and armature 215 and thence through the busy lamp L² 25 to battery. By this operation the attendant is notified that the trunk line has been seized.

The calling subscriber may now operate his calling device in accordance with the 30 first digit of the desired private automatic exchange subscriber's number. A series of interruptions is thereby produced in the circuit of the line relay 506 of the main connector H which deenergizes a corresponding 35 number of times. At each deenergization a circuit is completed extending from ground by way of armature 545 and its back contact, conductor 443, conductor 290, working contact of spring 271 of key K^{17} and the 40 said spring, armature 236 and its back contact, conductor 285, conductor 443, armature 547 and its front contact, armature 571 and its back contact, back contact and armature 555, through the winding of the relay 45 508, through the winding of the vertical magnet 581, and thence by way of the side switch wiper 577 in its first position to battery. Magnet 581 operates to raise the switch wipers of the main connector step by step until they are placed opposite the 55 level of bank contacts in which is located contacts associated with the line of the desired called subscriber. The slow acting relay 508 is of course energized in series with the vertical magnet and controls the operation of the private magnet 582 in advancing the side switch wipers of the main connector into their second position.

The calling subscriber in the main exchange may now operate his calling device for the next digit of the called subscriber's number. As before, a series of interruptions is produced in the line circuit of relay 506 which retracts its armature a plurality 60 of times in response thereto. At each re-

traction of its armature 545 an impulse of current is sent over the previously traced impulsing circuit. As the side switch wiper 577 is now in its second position the rotary magnet 580 will now be operated. Magnet 70 580 operates to rotate the switch wipers into engagement with the contact set of the desired called subscriber. The slow acting relay 508 is energized in series with the rotary magnet and following the termination 75 of the series of impulses to this magnet, allows the side switch wipers to advance to their third position, provided the line of the subscriber called is idle.

However, should the desired called subscriber's line be busy at this time the main connector H will be released in a manner described hereinbefore and the busy tone given to the calling subscriber.

The calling subscriber not being able to 80 connect with his party may desire to call another subscriber in the private automatic exchange. In order to do this he will operate his calling device for the digits comprising the local subscriber's number. In 85 response to these digits the auxiliary connector H' will be operated into connection with the line of this last called subscriber which we will assume is the line of the substation A⁴ terminated in the bank contacts 400-403, inclusive. Assuming this line to be idle when connection thereto is attempted by the connector H' there will be no ground potential present upon the test contact 402, and the private magnet 368 of the auxiliary 90 connector H' will therefore deenergize advancing the side switch wipers to their third position. A circuit is now completed for the switching relay 312 of the auxiliary connector H'. The switching relay upon energizing 95 completes a circuit extending from ground on release trunk conductor 444, armature 359 and its front contact, conductor 458, conductor 289, resting contact of spring 275 of key K^{18} and the said spring, 100 normally closed springs controlled by armature 235 and then through the winding of relay 207 to battery. Relay 207 is energized over this circuit and, upon operating, establishes a locking circuit for itself at armature 235 and at armature 236 opens the impulsing circuit of the calling subscriber. Switching relay 312, upon operating, also completes the ringing circuit of the subscriber at substation A⁴. When the called 105 subscriber answers the ring cut off relay 311 will be energized as will the back bridge relay 302. Relay 302, upon operating, completes the circuit of the slow acting release relay 304. The latter relay upon energizing, 110 prepares the operating circuits of the main connector H. It will be noted that upon the first off normal step of the connector H' the busy tone was removed from the calling subscriber's line. The calling sub- 115

120

125

130

scriber is now unable to operate the dual connectors though the called subscriber can by operating his calling device transfer the call to another desired party in the manner described before. This latter is due to the fact that the impulsing circuit controlled by line relay 506 including conductor 443 in Fig. 6 is opened at armature 236 in Fig. 4, while the back-bridge impulsing circuit paths relating to armature 523 in Fig. 6, and armature 319 in Fig. 7 are not disturbed.

It will now be assumed that the operator has operated the key K^{12} and that the calling subscriber in the main exchange has operated the main dual connector into connection with the called subscriber's line. The circuit for relay 207 is not closed upon the energization of either of the switching relays but is controlled by ring cut off relays 511 and 211 the circuit from relay 511 extending over the following path: Ground by way of front contact and armature 564, conductor 453, conductor 287, working contact of spring 275 of key K^{12} and the said spring, normally closed springs controlled by armature 235 and thence through the winding of relay 207 to battery. It will thus be seen that the calling subscriber is enabled to operate the dual connectors until a called subscriber answers, whereupon the relay 207 is energized, and he is then prevented from further operating the switch.

The calling subscriber may find it desirable to signal the attendant operator in order to obtain information from her as he may not know the number of the party with whom he desires to converse. In order to do this after seizing the trunk line comprising conductors 51 and 52 he will operate his calling device for the digit 1. By this operation an interruption is produced in the circuit of the line relay 506 and an impulse of current is sent over the operating circuit to the vertical magnet 581 of the main connector H. Another circuit is completed by the retraction of armature 545 which extends to the winding of the slow acting relay 307 to battery. The main connector H is of course raised opposite the first level in response to the operation of the vertical magnet. The cam 694 on the switch shaft operates the springs 689, 690, 691, 692, and 695 into engagement with each other and following the energization of the slow acting relay 508 a circuit is completed extending from ground by way of back contact and armature 551, spring 691, springs 690 and 689, conductor 448, front contact and armature 341, and thence through the winding of relay 314 to battery. A circuit completed in multiple with that of relay 314 extends from spring 690 by way of working contact of off normal spring 600 and the said spring through the release magnet 584 of the main connector H to battery. The

main connector H is accordingly restored to normal. Relay 314 upon energizing, completes a locking circuit which extends from ground on release trunk conductor 182, by way of spring 250 of key K^{12} and its resting contact, spring 259 of key K^{16} and its resting contact, conductor 294, conductor 463, armature 575 and its front contact, and thence through the winding of relay 314 to battery. Relay 314 also completes another circuit which extends from ground by way of front contact and armature 579, conductor 279 and its front contact, and thence through the calling lamp L^{10} to battery. By the operation of this signal the attendant operator is notified that the calling subscriber desires to communicate with her. In order to answer him she will throw either of her listening keys K^{12} or K^{16} thereby placing himself in communication with the calling subscriber. By the operation of key K^{12} or key K^{16} the answering lamp L^9 is lighted and the locking circuit of the relay 314 opened. Relay 314 of course deenergizes. After ascertaining what department the calling subscriber desires the operator may connect the calling subscriber with that department by means of the plug P^2 in a manner described before. When the conversation is terminated the release of the apparatus will take place in the usual manner.

The attendant operator in the private automatic exchange may under certain conditions wish to intercept all calls coming into the branch exchange. In order to do this she will leave both the keys K^{17} and $K^{17'}$ in their normal position. Under these conditions when a calling subscriber in the main exchange seizes the trunk line comprising conductors 51 and 52 the line relay 506 is energized as before described and the circuit of the slow acting release relay 507 completed. Relay 507 operates in the usual manner to ground the release trunk conductors 444 and 182. A circuit may now be traced extending from ground on release trunk conductor 182, armature 217 and its back contact, resting contact of spring 270 and the said spring, resting contact of spring 273 and said spring, and thence through the calling lamp L^4 to battery. By the operation of this signal the attendant is notified that there is a call on the trunk line and she will operate her listening key K^{12} in order to ascertain the desired subscriber's number. After securing the desired subscriber's number the operator if she finds that the subscriber called is accessible to the dual connectors will throw her dialling key K^{14} and operate her calling device for the digits of this local subscriber's number. When the dialling key is thrown in the conductors extending to the line relay 506 and the impedance coil 513 are bridged directly

by means of the calling device impulse spring. It will be seen that the operator by operating her calling device will cause the operation of the line relay 506 thereby causing the main connector H to connect with the line of the desired subscriber. When the calling device key K¹⁴ is thrown the circuit of the relay 205 is closed. This relay upon energizing, at armatures 231 and 232 supplies talking battery current to the calling subscriber and at armature 230 opens the circuit through the relay 505. The circuit of relay 505 now being opened the attendant is able to connect with any private automatic exchange subscriber's line regardless of whether he is barred or not. The operator may find it desirable instead of operating the dialling key K¹⁴ to throw the auxiliary dial key K¹⁵ and then operate her calling device. Under these conditions the impulses are sent to the vertical magnet of the main connector H over the following circuit: Ground by way of working contact of spring 249 of key K¹⁵ and the said spring, working contact of spring 248 of the calling device S and the said spring, conductor 285, conductor 442, armature 547 and its front contact, and armature 571 and its back contact, back contact and armature 555, through the winding of relay 508, through the winding of vertical magnet 581 and through the side switch wiper in the first position to battery. Vertical magnet 581 operates in the usual manner to raise the switch wipers opposite the level of bank contacts corresponding to the digit of the number called. Following the deenergization of the slow acting relay 508 which is energized in series with the vertical magnet the side switch wipers are stepped to their second position.

When the calling device of the attendant operator is operated for the last digit of the desired subscriber's number the impulses are sent over the previously traced impulse circuit through the rotary magnet 580, the side switch wipers being now in their second position. The rotary magnet operates to rotate the switch wipers 590-593, inclusive, into engagement with the bank contacts associated with the line of the desired substation. It will be assumed that the calling subscriber desired to communicate with one of the subscribers shown in the isolated private branch exchange shown in Fig. 10. The connector H is therefore operated into engagement with the bank contacts 615-618, inclusive. Assuming that this line is idle there will be no ground potential present upon the test contact 617 engaged by the test wiper 592 and the side switch will be stepped to its third position, following the termination of the series of impulses to the rotary magnet. When this occurs, a circuit of the cut off winding 717 of the line switch C⁷ will be operated thereby clearing the trunk line extending to the private branch exchange of its battery and ground connections in the line switch C⁷. The switching relay 512 will of course energize and ringing current will be intermittently projected over the trunk line to operate the bridged ringer 735 at the private branch exchange. The operator thereat upon hearing this signal will insert the plug of an idle cord circuit 75 which we will assume is the plug P⁴ of the cord circuit O' into the jack J⁸ and operate her listening key K²⁵. When the plug P⁴ is inserted into the jack J⁸ the ringer 735 is removed from across a bridge of the trunk conductors. Another result of the insertion of the plug P⁴ into the jack J⁸ is that a circuit is completed over the sleeve of the plug for the lamp L¹². When the key K²⁵ is thrown the operator's head set is bridged 80 across the conductors of the incoming trunk line and the ring cut-off relay 511 in the main connector H is accordingly energized. The back bridge relay 501 is also energized over the line circuit of the operator in the private branch exchange. Another result of the operation of the key K²⁵ is that the relay 725 is energized and it operates to open a point in the circuit of the lamp L¹² 85 and to establish a locking circuit for itself. By this operation the polarized relay 726 is also bridged across the trunk in order to maintain the back bridge relay of the main connector energized after the restoration of key K²⁵. The branch exchange operator 90 may now communicate with the attendant operator in the private automatic exchange in order to ascertain the number of the desired called subscriber in the private branch exchange. Having found that the subscriber at substation A⁷ is the one desired, she will test the line of this subscriber by means of the tip of her plug in order to ascertain whether it is busy or not. If the desired line is busy, there will be a ground 100 potential present upon the sleeve of the jack J⁹ and the relay 752 will be energized and will operate to flash the supervisory lamp L¹³ thereby notifying the branch exchange operator of the busy condition of this line. 105 The attendant operator in the private automatic exchange upon being informed of this condition by the branch exchange operator will communicate with the calling subscriber and tell him that the desired called line is 110 busy.

However, should the line of the substation A⁷ be idle when connection thereto is attempted by the branch exchange operator plug P⁵ will be inserted into the jack J⁹ 115 and the ringing key K²⁶ will be operated. As a result of the operation of key K²⁶ ringing current is projected out on the line of the called substation, it being of course understood that when the plug P⁵ is inserted 120

in the jack J^9 the circuit of the cut off relay 753 was completed and this relay operated to remove the normal battery and ground connections from the called subscriber's line. When the called subscriber answers the circuit of the supervisory relay 752 will be completed. This relay upon energizing, closes the circuit of the supervisory lamp L^{13} whereby the branch exchange operator is notified of the answering of the subscriber at substation A^7 and she will restore her listening key K^{25} to normal. Another result of the energization of relay 752 is that another circuit is completed for the relay 725 exclusive of the armature of the polarized relay. The calling subscriber in the main exchange may now converse with the subscriber in the private branch exchange over the heavy talking conductors battery being supplied to the subscriber in the main exchange from the winding of the line relay 506 and the winding of the impedance coil 513 and to the called subscriber at substation A^7 from the windings of the supervisory control relay 752. After the conversation is terminated if it should be found that the calling party desires a connection with another subscriber in the private automatic exchange he may inform the called subscriber of this. The called subscriber will then flash his receiver hook thereby intermittently lighting the supervisory lamp L^{13} and signaling the branch exchange operator. In response to the operation of this signal the operator will throw her listening key K^{25} and upon finding out the number of the subscriber desired in the automatic exchange she will throw her calling out key K^{24} thereby placing the calling device in bridge of the incoming trunk conductors and operate her calling device for the digits of the desired private automatic exchange party's number. By the latter operation two series of interruptions are produced in the circuit of the back bridge relay 501 of the main connector H and the auxiliary connector is operated in the usual manner into connection with this desired called subscriber's line. After dialling the digits of the called subscriber's number the operator will restore her calling out key K^{24} . In the meantime should the called subscriber at substation A^7 have had replaced his receiver upon the switchhook the operator being informed of this fact by the effacement of the lamp L^{13} will withdraw the plugs P^4 and P^5 from their associated jacks. However, if the subscriber at substation A^7 held the line when the called party in the branch exchange answered the relay 504 would be energized to reverse the battery over the trunk conductors extending to the private branch exchange and polarized relay 726 in the operator's cord circuit would be operated. As a result of this su-

pervisory lamp L^{12} would be lighted and the operator informed of the answer of the party in the private automatic exchange. When the conversation is terminated the subscribers will replace their receivers upon the switchhook. When the calling subscriber replaces his receiver the operated switches will be released in a manner described hereinbefore and by the effacement of the supervisory lamps L^{12} and L^{13} the branch exchange operator will be informed of the disconnection and she will withdraw the plugs of the cord circuit O' from their associated jacks.

Under certain conditions the attendant operator in the private automatic exchange may find it desirable to be able to release either one of the dual connectors. In order to do this the attendant operator is provided with a key for each dual connector. The key K^{20} is adapted to release the main connector H and the key K^{19} the auxiliary connector H' . The manner in which this release is accomplished will now be described. For this purpose it will first be assumed that the main connector H has been operated when the key K^{20} is operated. A circuit may now be traced from ground by way of the spring of key K^{20} and its working contact, conductor 288, conductor 433, working contact of off normal spring 397 and the said spring, and thence through the winding of the relay 509 to battery. Relay 509 upon energizing completes the release magnet circuit and the connector H is accordingly restored to normal. Had it been the auxiliary connector that it was desired to release the key K^{19} would have been operated. A circuit would then be traced from ground by way of spring of key K^{19} and its working contact, conductor 284, conductor 445, off normal spring 375 and its working contact, and thence through the winding of relay 309 to battery. By the energization of relay 309 the release magnet 367 is energized and the connector H' restored to normal.

Having described how connections are established from the main to branch exchange when the main exchange is operating automatically the description of the various connections when the main exchange is operating manually will now be briefly explained. In order to prepare the circuits of the manual exchange for operation the key K^1 and similar keys associated with the outgoing trunk lines extending to the private automatic exchange will be operated. As a result of the operation of these various keys the associated trunk lines will be busied in the banks of the selector repeaters and will be transferred to the operators' positions where they terminate in the jack J and similar jacks with their multiples.

In order to describe a call extending from

the manual exchange to the private automatic exchange it will be assumed that the main exchange operator desires to establish a connection with the subscriber at substation A⁵ in the private automatic exchange. The operator will therefore test the jacks of various trunk lines extending to the private automatic exchange with the tip of an idle cord circuit which it will be assumed is cord circuit O. Only the calling end of this cord circuit has been shown in detail but it will be understood that the circuits of the end terminating in plug P are of the usual design. Assuming that the trunk line terminating in jack J is the first idle trunk line the operator will insert the plug P' into the jack J. By this operation a circuit is completed over the sleeve of the plug for relay 31 and the cut off relay 34. Relay 31, upon energizing, completes a circuit for the supervisory lamp L. Relay 34, upon operating, removes the normal battery and ground connections from the incoming trunk line and at armature 42 completes a circuit of the slow acting relay 37. The operation of this latter relay is without function at the present time.

The operator will now throw her calling device key K² and operate her calling device for the digits of the desired private automatic exchange subscriber. As a result of the operation of the calling device the main connector H will be brought into engagement with the bank contacts 620-623, inclusive, which are the terminals of the line of the substation A⁵. Ringing current will be intermittently projected over the line of the called substation in the usual manner. When the subscriber answers the circuit of the ring cut off relay 511 will be completed and also that of the back bridge relay 501. The back bridge relay 501, upon operating, completes the circuit of slow acting relay 502. The latter relay, upon energizing, prepares the operating circuits of the auxiliary connector H' and at armature 527 completes the circuit of the solenoid 203. The solenoid, upon pulling up its plunger arm 220, completes the circuit of the reversing relay 201 which operates to reverse the battery over the incoming trunk line thereby causing the operation of the polarized relay 30 in the calling operator's cord circuit. Relay 30, upon energizing, opens the circuit of the supervisory lamp L thereby notifying the operator of the response of the branch exchange subscriber. When the conversation is terminated the release of the operated switches will take place in the same manner as before described.

The cord circuit O in the main exchange is arranged for reverse battery supervision. However, in its place may be used the cord circuit shown in Fig. 18 which is arranged for high resistance supervision. Under

these conditions the key K¹¹ in the trunk circuit at the private automatic exchange will be operated. It will now be assumed that the main exchange operator is using the cord circuit shown in Fig. 18 in order to call a subscriber in the private automatic exchange. As in the cord circuit O, only the circuits of the calling end of this cord circuit have been shown in full. When the plug of this cord circuit is inserted into an idle jack, J for instance, the supervisory relay 1201 will be energized in series with the cut off relay 34. Relay 1201, upon energizing, completes the circuit of the supervisory lamp L²⁸. In order to call the subscriber in the private automatic exchange, the operator will throw her calling device key K³⁰ and operate her calling device for the digits of the desired called subscriber. When the called party answers instead of the circuit of relay 201 being closed relay 202 will be energized. By the operation of relay 202 the resistances R and R', normally included in the incoming line conductors, will be short circuited and the marginal relay 1202 in the main exchange operator's cord circuit energized. Relay 1202, upon operating, opens the circuit of the supervisory lamp L²⁸ thereby informing the calling operator of the response of the called subscriber. The subsequent operation when the call is transferred to another private automatic exchange subscriber or the connection released takes place in the same manner as was described hereinbefore.

Under certain conditions in the above connections the attendant operator upon responding to the call may find it desirable to signal the main exchange operator. In order to do this she will operate the key K¹³ whereby the circuit of the relay 201 or that of the relay 202 will be intermittently opened depending upon whether the key K¹¹ is in its normal or operated position. By this operation, the polarized relay 30 or the marginal relay 1202 in the calling operator's cord circuit will be intermittently energized and deenergized and the lamp L or L²⁸ flashed. This operation would serve to signal the main exchange operator and she would operate her listening key K' or K³¹ in order to ascertain what was desired.

It will be noted that there is a jack J² associated with the trunk line comprising conductors 51 and 52 in the main automatic exchange. This jack is located at the wire chief's desk and may be used by him for testing this trunk line whenever necessary. However, these operations are well known and, as they form no part of the present invention need not be described herein.

Associated with each incoming trunk line at the attendant's cabinet in the private automatic exchange is a key similar to the key K⁷, associated with the trunk line comprising

ing conductors 51 and 52. These keys are for the purpose of busying any one of the incoming trunk lines in the main exchange in case the trunk line is out of order. In order to describe this operation it will be assumed that the trunk line shown in the drawings is out of order. Under these conditions the attendant operator will throw the key K^1 . By this operation battery is placed on the conductor 51 of the trunk line. The relay 16 or the relay 36 (depending upon whether the main exchange is operating automatically or manually) will be energized. Relay 16, upon energizing, places a busy potential upon the multiplied test contact of the trunk line in the banks of the selector repeaters at armature 20 and at the same time places a busy potential on the test jack J^2 . Should the main exchange be operating manually at this time the relay 36 would be energized and a busy potential would be placed on the sleeves of the multiplied jacks of the trunk line.

The above is the normal operation in the system during the daytime. At night, however, the subscribers at the various local stations in the private automatic exchange will not be there and provision must be made to handle night calls. The manner in which this is accomplished will now be described. The night calls coming in over the various trunk lines extending to the private automatic exchange will be directed to a certain local substation where the night watchman or whoever is in charge of the business at night is located. The various night plugs P^2 and similar ones associated with the incoming trunk lines, are placed in the jacks J^{21} , and J^{22} , Fig. 20, and the plug P^{20} is inserted into the jack associated with the line of the desired local substation which is to be used for night service. The night keys similar to key K^1 in the various night plugs will be operated by the attendant operator before she leaves her position. The manner in which a call is extended to the local substation when the above connections are made will now be described, it being assumed that the plug P^{20} has been inserted into the jack J^{16} associated with the local substation A^8 which is the one to be used for night service. For this purpose we will assume that a calling subscriber in the main exchange has seized the trunk line comprising conductors 51 and 52 by means of the selector repeater E. When this occurs the circuit of the line relay 506 of the main connector H will be completed and this relay will immediately energize. Relay 506, upon operating, completes the circuit of the slow acting relay 507. The latter relay immediately energizes and places ground on the release trunk conductors 444 and 182. A circuit is then completed extending from ground on release trunk conductor 182 by

way of working contact of spring 177 of key K^{10} and the said spring, back contact and armature 162, and thence through the winding of the relay 104 to battery. Relay 104, upon energizing, completes a circuit 70 of the relay 106. Relay 106, upon operating, places ground on the sleeve of the plug P^2 in order to operate the holding winding 926 of the line switch C^8 thus clearing the line of the night substation from its normal battery and ground connections in the line switch C^8 and to complete the ringing circuit. It will be seen that ground will be extended over the sleeve of the plug P^2 to the sleeve of the various jacks associated 80 with the interconnecting night service circuit shown in Fig. 20 to the sleeves of the various night plugs associated with the incoming trunk lines to the winding of the cut off relays in the various incoming trunk circuits similar to relay 105 associated with the trunk line shown in the drawings. These relays upon energizing, place a battery potential upon the upper line conductors of the various incoming trunk lines. By this operation the relays in the line switches associated with these trunk lines similar to relay 16 in the line switch C are operated. When this occurs a ground potential is placed upon the bank contacts of these trunk lines accessible to the selector repeater and also to the jacks similar to J^2 at the wire chief's desk. By this means all the trunk lines connected to the night service circuit are rendered busy in the main exchange. 106

Returning now to the operation of the circuit when the relay 106 energizes ringing current is intermittently applied to the line of the substation A^8 until the watchman thereat removes his receiver from the switch-hook. When this occurs the circuit of the ring cut off relay 107 is completed and the line of the called substation is extended to the back bridge relay 110 which supplies talking current to the watchman at substation A^8 . Back bridge relay 110 is of course energized over the called subscriber's line loop and upon operating completes the circuit of the slow acting relay 111. It will be seen that the watchman on the night plug 110 is now in communication with the calling subscriber and that he may by operating his calling device control the operation of the main dual connector H in the same manner as was described hereinbefore in connecting 120 with the line of another subscriber in the private automatic exchange. This called subscriber, upon answering, is of course, enabled to release the watchman from the connection or be released by him and is also 125 enabled to pass the call by means of the auxiliary connector H' to the line of another subscriber. All these operations have been described before and will be readily understood. 130

An alternative arrangement by which the various incoming trunk lines can be associated together by means other than the interconnecting night service circuit shown in Fig. 20 will now be described. Instead of the various night plugs associated with the incoming trunk lines being inserted into jacks J^2 and similar jacks, the switches S^1 , S^2 , etc., will be operated. It will be seen that this accomplishes practically the same result as the circuit shown in Fig. 20 and that when one of the trunk lines is seized the cut off relays associated with the other incoming trunk lines will be accordingly energized in order to busy the associated trunk lines in the main exchange.

Should the calling subscriber desire to call a particular number in the branch exchange he may do so. Immediately upon seizing a trunk line extending to the private automatic exchange the same operation as before described will occur. However, as soon as the calling device is operated in accordance with the first digit of the desired number, the main selector switch H^1 is raised to the proper level under the control of the line relay 506 in the usual manner. Upon the first vertical step of the switch a circuit is completed extending from ground by way of springs 692 and 695, conductor 472, conductor 192, back contact and armature 156, and thence through the winding of relay 109 to battery. Relay 109 is energized over this circuit and, upon operating, establishes a locking circuit for itself at armature 161 and at armatures 159, 160, and 163 completely disassociates the plug P^2 from the incoming trunk line. By this latter operation the ringing of the watchman is stopped and the busy potential is removed from the trunk lines connected for night service by the switches S^1 and S^2 in the main exchange. The subsequent operations by which a connection is established with the desired local substation will take place in the usual manner.

Having described various connections between the main and private automatic exchanges a number of connections local to the private automatic exchange will now be described. For this purpose it will be assumed that the subscriber at substation A^4 desires to call the subscriber at substation A^8 and it will be assumed further that at the time this connection is desired the night plug P^2 associated with the incoming trunk line comprising conductors 51 and 52 is inserted into the jack J^6 and that the incoming trunk line is idle.

When the receiver is removed at substation A^4 a circuit is completed for the line relay 700 over the two sides of the calling line in series. Relay 700, upon energizing, completes the circuit of the pull down winding 703 of the individual line switch C^4 . The pull down winding, upon energizing, attracts the plunger arm 706 and the cut off armature 705. The cut off armature opens the circuit of the line relay and the plunger arm 706 upon being operated forces the springs 750-753, inclusive, into engagement with their working contacts thereby extending the line of the substation A^4 to an idle first selector switch which we will assume is the first selector D^2 . By the engagement of the spring 752 with its working contact ground is extended along the conductor 760 to the master switch bank (not shown) whereby the master switch is caused to move the plunger arms of all idle line switches opposite an idle trunk line. Upon the line of the substation A^4 being extended to the selector D^2 the line relay 800 thereof is energized over the two sides of the calling line in series. Upon attracting its armature 810, the circuit of the slow acting relay 801 is completed. Relay 801, upon energizing, at its armature 812 prepares the circuits of the selector D^2 for operation and at armature 811 places ground on release trunk conductor 783, thereby establishing a holding circuit for the line switch C^4 which extends by way of working contact of spring 751 and the said spring, and thence through the holding winding 702 to battery. The energization of the holding winding 702 serves to maintain the plunger arm 706 and the cut off armature 705 in their operated position. It will be understood that the above traced holding circuit is established before the slow acting line relay 700 has time to deenergize. A branch of this holding circuit also extends by way of the private normal conductor 639 to multiply connected test contacts in the banks of connector switches which have access to the line of the substation A^4 whereby the line is rendered busy. Another branch of the holding circuit also extends to the multiple line jacks similar to jack J^6 associated with the line of the substation A^4 at the attendant's cabinet.

The calling subscriber may now operate his calling device in accordance with the first digit of the desired subscriber's number. By this operation a series of interruptions is produced in the circuit of the line relay 800 of the selector D^2 which deenergizes a corresponding number of times. At each deenergization, an impulse of current is sent over a circuit extending from ground, by way of back contact and armature 822, armature 810 and its back contact, armature 812 and its front contact, winding of the slow acting relay 802, and thence through the winding of the vertical magnet 808 to battery. Magnet 808 operates to raise the switch wipers 830-832, inclusive, opposite the desired level of bank contacts. The slow acting relay 802 is energized in series with

the vertical magnet and upon the first vertical step of the shaft, the off normal springs 835 and 836 being operated, a circuit is completed extending from ground on release of trunk conductor 816, by way of armature 815 and its front contact, off normal spring 836 and its working contact, and through the winding of the stepping relay 803 to battery. Relay 803, upon energizing establishes a locking circuit for itself at armature 817, and at armature 818 prepares the circuit for the rotary magnet. Upon the termination of the vertical movement of the switch the slow acting relay 802 deenergizes and an impulse of current is sent to the rotary magnet 807. Magnet 807, upon operating, rotates the switch wipers into engagement with the first set of bank contacts in the selected level and at armature 825 breaks the locking circuit of the stepping relay 803. The further operation of the selector D^2 depends upon whether the trunk line with which the switch wipers are associated is or is not busy. If busy there will be a ground potential present on the test contact engaged by the test wiper 831 and a circuit will be completed for the stepping relay 803. Relay 803 will operate to establish a locking circuit for itself and to complete the rotary magnet circuit. Magnet 807 will operate to rotate the switch wipers into engagement with the next set of bank contacts in the selected level and to break the locking circuit of the stepping relay 803. The alternate operation of stepping relay 803 and the rotary magnet 807 will continue until an idle trunk is found, which, we will assume, is the trunk line terminating in bank contacts 835-837, inclusive. As this trunk line is idle, there will be no ground present upon the test contact 836 engaged by the test wiper 831. The switching relay 804, being no longer short circuited, will energize in series with the stepping relay 803. Switching relay 804, upon energizing, disconnects the line conductors of the substation A^4 from the windings of the line relay 800 and extends them by way of armatures 820 and 823, wipers 830 and 832, normally closed springs controlled by armatures 874 and 878, to the upper and lower windings of the line relay 850 of the connector H^2 . The line relay 850 energizes over the calling subscriber's line loop and, upon operating, completes the circuit of the slow acting relay 851 at armature 865. Relay 851, upon operating, prepares the impulsing circuits of the connector H^2 at armature 867 and at armature 866 places ground on release trunk conductor 868 thereby establishing a holding circuit which extends by way of test contact 836, test wiper 831, armature 821 and its front contact, where the circuit divides one path extending back to holding winding 702 of the line switch C^4 , the other through the switching relay 804. This holding circuit

serves to maintain the line switch C^4 and the selector D^2 in their operated positions.

The calling subscriber may now operate his calling device for the next digit of the called subscriber's number. By this operation a series of interruptions is produced in the line circuit of the relay 850 which de-energizes a plurality of times in response thereto. At each retraction of its armature 865 an impulse of current is sent over the following circuit: Ground by way of armature 865 and its back contact, armature 867 and its front contact, off normal spring 870 and 871, winding of the slow acting relay 852, and thence through the winding of the vertical magnet 861 to battery. The above is the circuit over which the first impulse to the vertical magnet is sent. Upon the first vertical step of the switch shaft the off normal springs are shifted and the remaining impulses to the vertical magnet traverse a new path which is the same as the one previously traced except that it includes the off normal springs 870 and 872 and armature 876 and its front contact. Magnet 861 operates to raise the switch wipers 900-902, inclusive, step by step until they are placed opposite the level of bank contacts in which is located the contact set associated with the line of the substation A^8 . The slow acting relay 852 energizes in series with the vertical magnet and maintains its armatures attracted throughout the vertical movement of the switch and at the termination thereof deenergizes and transfers the impulsing circuit to the rotary magnet 859.

The calling subscriber may now operate his calling device in accordance with the third and final digit of the desired called subscriber's number. As before, a series of interruptions is produced in the circuit of the line relay 850 which retracts its armature a corresponding number of times each time sending an impulse of current over a circuit extending from ground, by way of armature 865 and its back contact, armature 867 and its front contact, off normal springs 870 and 872, armature 876 and its back contact, normally closed springs controlled by armature 886, back contact and armature 896, and thence through the winding of the rotary magnet 859 to battery. Magnet 859 operates to rotate the switch wipers 900-902, inclusive, into engagement with the set of bank contacts associated with the line of the substation A^8 , which, we will assume, are the bank contacts 938-940, inclusive. The slow acting relay 857 is energized in multiple with the rotary magnet and operates to connect the test wiper 901 to the test relay 856.

Should the desired line be busy at this time there will be a ground potential present on the test contact 939 engaged by the test wiper 901. A circuit is then completed

extending from the said grounded test contact by way of the test wiper 901, normally closed springs controlled by armature 895, armature 890 and its front contact, armature 883 and its back contact, and through the winding of the busy relay 856 to battery. Relay 856, upon energizing, establishes a locking circuit for itself at armature 885 and at armature 887 places a busy tone on the calling subscriber's line. Upon hearing this tone, the calling subscriber will replace his receiver upon the switchhook thereby initiating the release of the operated switches in a well known manner.

115 It will now be assumed that the line of the substation A⁸ was idle when connection therewith was attempted by the connector H². Under these conditions there will be no ground potential present upon the test contact engaged by the test wiper 901 and no circuit will be completed for the busy relay 856. Then, following the deenergization of the slow acting relay 857, a circuit is completed extending from ground on release 20 of the trunk conductor 868, by way of armature 885 and its back contact, lower winding of switching relay 868, back contact and armature 890, normally closed springs controlled by armature 895, test wiper 901, test contact 39, and thence through the holding winding 926 of the line switch C⁸ to battery. Holding winding 926 and the switching relay 868 are energized over this circuit. The holding winding, upon energizing, attracts 25 the cut-off armature 928 thereby disconnecting the line of the substation A⁸ from its normal battery and ground connections in the line switch C⁸. A branch of this circuit also extends by way of the sleeve of the jack J¹⁶, sleeve of the plug P², back contact and armature 160, armature 149 and its back contact, and thence through the winding of the cut off relay 105 to battery. The plug P² has been inserted into the jack J¹⁶ in order 30 to connect the substation A⁸ for night service. Relay 105, upon energizing, at armature 147 places battery on the upper conductor 51 of the incoming trunk line whereby the relay 35 or 16 in the main exchange is energized and a busy potential placed upon the terminals of the trunk line either at the jack or in the automatic exchange. In case the main exchange operator neglects the busy test and inserts the 35 jack of an idle cord circuit into the jack J preparatory to extending the call to the private automatic exchange by way of the dual connectors the line relay 506 of the main connector H will be energized in the usual manner as will the slow acting release relay 507. The latter relay operates to ground the release trunk conductors 444 and 182. By this latter operation the relay 104 is energized and a busy tone is now given 40 to the operator over a circuit extending from the busy machine by way of front contact and armature 146, front contact and armature 141, through the condenser, back contact and armature 129, normally closed springs controlled by armature 120, and thence to the trunk conductor 51. The operator, upon hearing this busy tone, will know the trunk line is busy and will withdraw the plug of her cord circuit from the jack J.

45 Returning now to the operation of the connector switch H², relay 858, upon energizing, establishes a locking circuit for itself at its armature 894, and at armatures 893 and 897 completes the ringing circuit. Ringing current is intermittently applied to the line of the substation A⁸ until an answer is obtained. When this occurs the ring cut-off relay 855 will be reenergized. Upon operating, this relay establishes a locking circuit for itself at armature 882 and at armatures 881 and 883 opens the ringing circuit and at the front contacts of these armatures completes the circuit of the back bridge relay 853. Relay 853, upon energizing, reverses the normal battery flow over the calling subscriber's line in the usual manner and for any desirable purpose. Conversation may now be carried on between the subscribers at substation A⁴ and A⁸ over the heavy talking conductors, talking battery being supplied to the calling subscriber from the windings of the line relay 850 of the connector H² and to the called subscriber from the windings of the back bridge relay 853. When the conversation is terminated the release of the switches H², D² and C⁸ will take place in the usual manner upon the calling subscriber replacing his receiver upon the switchhook.

50 The above is the description of the local call when the called substation is preconnected for night service. Calls made when the called substation is not so connected will take place in the same manner as described above except that the plug P² or a similar plug will not be inserted in the jack of the called substation and the associated cut-off relay similar to relay 105 in the trunk circuit will not be energized.

55 The manner in which a connection is established between a local subscriber and a subscriber in the private branch exchange will now be described it being assumed for this purpose that the subscriber at substation A⁴ desires to call the subscriber at substation A⁵. When the receiver is removed at substation A⁴ the line relay 700 is energized over the calling subscriber's line loop and completes a circuit for the pull down winding 703 of the line switch C⁵. Upon energizing, the pull down winding moves both the cut off armature and the plunger arm. The cut off armature 705, upon operating, disconnects the line relay 700 and the 60

plunger arm 706 by forcing the springs 750-753, inclusive, into engagement with their working contacts extends the calling subscriber's line to an idle first selector switch. It will be assumed that the calling subscriber's line is extended to the selector switch D².

In response to the first operation of the calling device at substation A⁴ the selector switch D² will be raised to the desired level and operate to select a trunk line extending to an idle connector switch, which, we will assume, is the trunk line terminating in bank contacts 835-837, inclusive. When this occurs the switching relay 804 will be energized and operate to disconnect the incoming trunk line from the windings of the relay 800 and extend them to the windings of the line relay 850 of the selected connector H². All the foregoing operations take place in the same manner as was described fully hereinbefore.

As the trunk line leading to the private branch exchange terminates in the ninth level of the connector switch the calling subscriber at substation A⁴ will operate his calling device in accordance with this digit. By this operation nine interruptions are produced in the circuit of the line relay 850 and the connector H² is raised opposite this level. The springs 905 and 906 are shaft springs adapted to be operated when the switch shaft is raised opposite the ninth level. When this occurs a circuit will be completed extending from ground on release trunk conductor 868, shaft spring 906, shaft spring 905, spring 909' and its resting contact, armature 875 and its front contact, armature 883 and its back contact, and thence through the winding of the relay 856 to battery. Relay 856, upon energizing, establishes a locking circuit for itself at armature 885 and at armature 886 prepares the rotary magnet circuit. Upon the termination of the vertical movement of the switch the slow acting relay 852 is deenergized and an impulse of current is sent to the rotary magnet 859 over a circuit extending from ground on release trunk conductor 868 by way of shaft springs 906 and 905, spring 909' and its resting contact, armature 875 and its back contact, armature 886 and its front contact, back contact and armature 896, and thence through the winding of the rotary magnet 859 to battery. Magnet 859 operates to rotate the switch wipers into engagement with the first set of bank contacts in the ninth level and to open the locking circuit of the relay 856. The slow acting relay 857 is energized in multiple with the rotary magnet and operates to connect the test wiper 901 to the relay 856. The further operation of the switch depends upon whether or not this trunk line is busy. If busy, there will be

a ground potential present upon the test contact engaged by the test wiper 951 and the relay 856 will be again energized to complete the rotary magnet circuit. Magnet 859 will operate to rotate the switch wipers into engagement with the next set of bank contacts in the ninth level. The alternate operation of relay 856 and the rotary magnet 859 will continue until an idle trunk is found which, we will assume, is the trunk line terminating in bank contacts 934-936, inclusive. When this occurs there will be no ground potential present upon the test contact 935 engaged by the test wiper 901 and no circuit will be completed for relay 856. Then, following the deenergization of the slow acting relay 857, a circuit is completed extending from ground on release trunk conductor 868, armature 885 and its back contact, lower winding of the switching relay 858, back contact and armature 890, normally closed springs controlled by armature 895, test wiper 901, test contact 935, conductor 779 and thence through the holding winding 717 of the line switch C⁴ to battery. The relay 858 and the holding winding 717 are energized over this circuit. The holding winding 717, upon energizing, removes the normal battery and ground connections from the outgoing trunk line in the line switch C⁴. Relay 858, upon energizing, establishes a locking circuit for itself at armature 894 and at armatures 893 and 897 completes the ringing circuit. Ringing current is now intermittently projected out on the trunk line in order to operate the bridged ringer 735 in the same manner as if this trunk line were a called local line. The operator in the private branch exchange upon hearing the signal 735 will answer the call by inserting the plug of an idle cord circuit into the jack J⁸. The subsequent operations by which the connection is extended to the substation A⁷ will take place in the same manner as was described before. When the conversation is terminated the release of the apparatus will take place in the usual manner.

As before mentioned, the private automatic exchange is provided with an information, complaint, and attendant operators. The manner in which a local substation signals the information operator will now be described it being assumed that the subscriber at substation A⁴ desires to call the information operator. In order to do this he will remove his receiver and operate his calling device for the digits 22. When the receiver is removed at substation A⁴ line switch C⁴ is operated in the usual manner to extend the calling subscriber's line to the line relay of an idle selector switch D².

In response to the first 2 being called on the calling device at substation A⁴ the se-

lector D² is operated in the usual manner to the second level after which it automatically rotates to select an idle connector switch and extend the calling subscriber's line to the line relay thereof. It will be assumed that the connector switch H² was selected for use. The line and release relays of this switch are energized as before described and with the same results.

When the calling device at the calling substation is operated for the next digit 2 of the information operator's number the connector switch H² is raised to the second level in the usual manner. The springs 909 and 910 are shaft springs which are adapted to operate when the switch shaft is raised to the first level while all the springs 909, 910, 911 and 912 are adapted to be operated when the switch shaft is raised opposite the second level. By the operation of the springs 911 and 912 a circuit is completed extending from ground through the winding of relay 854, spring 911, spring 912, and thence through the lower winding of the ring cut off relay 855 to battery. Relays 854 and 855 are energized over this circuit, relay 855 completing a locking circuit for itself and preparing a point in the signalling circuit to the information operator. By the engagement of springs 909-910, the circuit of the relay 856 is completed and it operates to establish a locking circuit for itself and to prepare the circuit of the rotary magnet 859. Following the termination of the vertical movement of the shaft, the slow acting relay 852 is deenergized and the rotary magnet circuit completed. The selection of an idle trunk extending to the information operator takes place in the same manner as was described in the selection of a trunk extending to the private branch exchange. It will be assumed that the trunk line terminating in bank contacts 946-948, inclusive, is the one selected for use by the connector H². When this occurs there will be no ground potential present upon the test contact 947 engaged by the test wiper 901 and no circuit will be completed for the relay 856. Then, following the deenergization of the slow acting relay 857 the switching relay 858 is energized. Upon operating, this relay establishes a locking circuit for itself at armature 894 and at armatures 893 and 897 completes the signalling circuit to the information operator. It will now be seen that there is a bridge extending across the talking conductors of the connector H² which extends from the wiper 900, front contact and armature 893, armature 881 and its front contact, armature 889 and its back contact, upper winding of the impedance coil 853, armature 879 and its front contact, front contact and armature 880, lower winding of the impedance coil 853, front contact and armature 883, armature 897 and its front contact, to wiper 902. The line relay 1116 of the selected information operator's trunk circuit, Fig. 15, is immediately energized over the two sides of the trunk line in series. Upon operating relay 1116 at its 70 armature 1117 completes the circuit of the line lamp L³¹. The impedance coil 853, being included in the above circuit, will also be energized. However, due to a mechanical interlocking device controlled by the armature of the relay 854, which is now operated, the energization of the coil 853 has no effect upon its armatures. The construction of the interlocking device is shown in Fig. 11^a. It will be seen that unless the relay 854 is deenergized relay 858 cannot attract its armatures. The information operator, upon noting the operation of the line signal will insert the plug of an idle cord circuit of any well known type into the jack J³⁵ 85 in order to answer the call. When the plug is inserted into the jack the cut off relay 1115 is energized and the circuit of the line relay 1116 is opened which deenergizes opening the circuit of the line lamp L³¹. The operator will now throw the listening key in his cord circuit in order to communicate with the calling subscriber and give him the information he desires. When the conversation is terminated the calling subscriber will 90 replace his receiver upon the switchhook thereby releasing the operated switches in the usual manner.

Should the calling subscriber at substation A⁴ have desired to communicate with the complaint operator, he would have dialled the digit 1 for the final digit instead of 2. By this operation the connector H² would have been raised to the first level whereupon the springs 909 and 910 would 105 be forced into engagement. The springs 909 and 910 are in multiple with the springs 905 and 906 which are operated when the connector H² was raised to the ninth level. The subsequent operations by which an idle trunk is seized leading to the complaint operator and ringing current impressed thereon will take place in the same manner as was described when the connector H was operated to the ninth level and hence will be 110 readily understood. It will be assumed that the bank contacts 950-952, inclusive, constitute the terminals of the idle trunk line seized. When ringing current is impressed over this line the bridged ring up relay 1102 115 in the complaint operator's trunk circuit shown in Fig. 14 is energized and upon operating, completes the circuit of the relay 1101. Relay 1101, upon operating, establishes a locking circuit for itself at armature 1106 and at armature 1107 completes a circuit for the line lamp L³⁰. This signal serves to notify the complaint operator that this trunk has been seized and she will 120 answer the call in the same manner as did 125

130

the information operator. As before, when the calling subscriber replaces his receiver upon the switchhook the connection is released.

- 5 The local subscribers in the branch exchange may find it necessary to signal the attendant operator in order to ask that operator to obtain a connection for them with another local subscriber at some later time
 10 or for any other reason. In order to do this the local subscriber will remove his receiver and operate his calling device for the digit 1. For the purposes of description it will be assumed that the subscriber
 15 at substation A⁴ desires to call the attendant operator. As before, when the receiver is removed at the calling substation the line switch C⁴ is operated to extend the calling line to an idle selector switch which
 20 we will assume is the selector D². The line and release relays 800 and 801 of this selector are energized as before described and with the same results.
 25 When the calling device is operated for the digit 1 an interruption is produced in the circuit of the line relay 800 and the selector D² is stepped to the first level after which it operates automatically to select an idle trunk leading to the attendant operator.
 30 We will assume in the present case that the trunk line terminating in bank contacts 840-842, inclusive, is the idle trunk line selected by the selector D². When this occurs, the switching relay 804 will be energized and the calling subscriber's line will be extended to the trunk circuit of the attendant operator shown in Fig. 16. The line relay 1126 will be immediately energized over the two sides of the calling line in series. Upon energizing, this relay closes a holding circuit at its armature 1139 for the selector D² and the line switch C⁴ by placing ground on release trunk conductor 961 and at armature 1138 closes the circuit
 40 of the line lamp L³⁴ before the attendant operator. Upon perceiving the operation of the signal L³⁴ the attendant operator will respond to the call by inserting the plug of an idle cord circuit into the jack J³⁴ and operating her listening key. When the plug is inserted into the jack J³⁴ the cut off relay 1125 is energized over the sleeve of the plug and operates to place ground on release trunk conductor 961 at armature 1131 and at armatures 1130 and 1132 opens the circuit of the line relay 1126 which deenergizes extinguishing the line lamp L³⁴. Having informed the attendant operator that he desires to obtain a connection with the subscriber at substation A⁸ at some later time the calling subscriber at substation A⁴ will replace his receiver upon the switchhook and the connection will be released in the well known manner.
 60 At the predetermined time the attendant

operator will test the line of the substations A⁴ and A⁸ and if they are idle, will insert the plugs of an idle cord circuit such as the one shown in Fig. 12, for instance, into the jacks associated with the substations A⁴ and A⁸ it being assumed that the plug P⁶ is inserted into the jack J⁶ and the plug P⁷ into the jack J¹⁶. By this operation the holding winding 702 and the holding winding 926 are energized over the sleeve of the associated plugs as are the relays 1001 and 1009. The holding windings, upon energizing, operate in the usual manner to disconnect the lines of the substations A⁴ and A⁸ from their normal battery and ground connections in their individual line switches. Relay 1001, upon energizing, completes the circuit of the supervisory lamp L¹⁵ at armature 1121 and relay 1009, upon energizing, completes the circuit of the supervisory lamp L¹⁷ at armature 1051. In order to signal the two subscribers the operator will operate the ringing keys K²⁹ and K³¹. When the subscribers answer the relays 1002 and 1008 will be energized in series with the called lines. Talking battery will be supplied to the subscriber at substation A⁴ from the windings of the impedance 1005 and to the subscriber at substation A⁸ from the winding of the impedance coil 1006. Relay 1002, upon energizing, opens the circuit of supervisory lamp L¹⁵ at armature 1023, at armature 1024 closes the circuit of the relay 1003 and at armature 1025 closes the circuit of the relay 1004. Relay 1003, upon energizing, establishes a locking circuit for itself at armature 1028 and at armature 1027 prepares the circuit of the supervisory lamp L¹⁶. Relay 1008, upon energizing, completes the circuit of the relay 1007 at armature 1046 and extinguishes the supervisory lamp L¹⁷ at armature 1045. Relay 1007, upon energizing, establishes a locking circuit for itself at armature 1042 and at armature 1043 prepares the circuit of the supervisory lamp L¹⁸. When the conversation is terminated both subscribers will replace their receivers upon their respective switchhooks. When this occurs the circuits of the relays 1002 and 1008 will be opened and these relays will then be energized. Relay 1002, upon deenergizing, completes a circuit extending from ground, by way of front contact and armature 1021, armature 1024 and its back contact, front contact and armature 1027, where the circuit divides one path extending through the winding of the relay 1000 to battery and the other path extending through the lamp L¹⁶ to battery. Relay 1000, upon energizing, establishes a locking circuit for itself at armature 1016 and at armature 1017 disconnects the sleeve of the plug P⁶ from the winding of the slow acting relay 1001 and transfers it to the winding of the high resistance relay 1004. The opera- 125
 130

tion of the supervisory lamp L^{16} serves to notify the attendant operator that the subscriber at substation A^4 has replaced his receiver upon the switchhook. Relay 1004 is energized in series with the holding winding of the line switch C^4 but it does not permit enough current to flow over its circuit to maintain the holding winding 702 energized. Relay 1004, upon energizing, places ground by way of resting contact of spring 1062 of key K^{29} and said spring, spring 1061 and its resting contact, front contact and armature 1029, armature 1016 and its front contact, through the winding of relay 1000 to battery. This circuit serves to maintain the relay 1000 energized after the deenergization of the slow acting relay 1001. The line of the substation A^4 is now idle and the subscriber thereat is able to call or be called as his line is completely disassociated from the cord circuit shown in Fig. 12 by the energization of the relay 1000. Should the operator desire to recall the subscriber at substation A^4 she may do so by operating her ringing key K^{28} . The locking circuit of the relay 1000 is thereby opened and this relay deenergizes again connecting the line of the subscriber at substation A^4 to the cord circuit. The operation of the relays at the opposite end of the cord circuit is the same as was described in connection with the relays associated with the plug P^6 and this operation will be readily understood from the above description.

Should the attendant operator at any time disregard the busy test on the sleeve of the line jacks and insert the plug P^6 or P^7 into the jack of a busy line she will be notified that the line is busy. Assuming that the plug P^6 is inserted into the jack of a busy line the relay 1002 will be energized over two sides of the associated line in series. Relay 1002, upon operating, completes a circuit extending from ground by way of front contact and armature 1023, back contact and armature 1030, armature 1020 and its back contact, through the winding of the relay 1000 to battery, and through the winding of the lamp L^{16} to battery. Relay 1000 operates to disassociate the called line from the cord circuit and the lamp L^{16} serves to notify the operator that the called line is busy.

As before mentioned, the incoming trunk line comprising conductors 51 and 52 is a two way trunk line and is adapted to be used for calls extending from the private automatic to the main exchange. In order to describe its operation under these circumstances it will be assumed that the subscriber at substation A^4 desires to obtain a connection with a subscriber in the main exchange when the main exchange is operating automatically. In order to do this the subscriber at substation A^4 will remove his receiver and operate his calling device with the digits 5, 10, 15, 20, 25, 30, 35, 40, 45, 50, 55, 60, 65, 70, 75, 80, 85, 90, 95, 100, 105, 110, 115, 120, 125, 130.

When the receiver is removed at substation A^4 the line switch C^4 operates in the well known manner to extend the line of the calling subscriber to an idle first selector switch which we will assume is the selector D^2 . The line relay 800 thereof is energized over the two sides of the calling line in series and upon operating completes the circuit of the slow acting relay 801. Relay 801 operates in the usual manner to complete the holding circuit of the line switch C^4 .

When the calling device is operated in accordance with the first digit 2, two interruptions are produced in the circuit of the line relay 800 and the selector D^2 is stepped to the second level whereupon it automatically rotates in search of an idle trunk line extending to the local main exchange. It will be assumed that the trunk line terminating in bank contacts 835-837, inclusive, is the first idle trunk line and is the one selected for use by the selector D^2 . When this occurs the switching relay 804 is energized and extends the calling subscriber's line to the windings of the line relay 850 of the local connector H^2 .

When the calling device is operated for the last digit 0, then interruptions are produced in the circuit of the line relay 850. The switch wipers 900-902 of the connector H^2 are accordingly raised opposite the tenth level of the bank contacts. When the switch wipers are raised opposite the tenth level the springs 905-908, inclusive, are operated and the circuits of the switch altered in the same manner as was described when the connector H^2 was operated opposite the second level of bank contacts. The connector H^2 will now automatically rotate in search of an idle trunk line. It will be assumed that the trunk line comprising conductors 51 and 52 and terminating in bank contacts 930-932 is the first idle trunk line and is the one selected by the connector H^2 . When this occurs, there being no ground potential present upon the test contact 921 engaged by the test wiper 901, the switching relay 858 will be energized. Relay 858, upon operating, establishes a locking circuit for itself at armature 894 and at armatures 893 and 897 completes the operating circuit of the line switch C associated with the trunk line in the main exchange. The conductors 970-972, inclusive, are multiples of the incoming trunk line comprising conductors 51 and 52 in the banks of the local connector switches and may be seen in Fig. 3. It will be noted that the cut off relay 102 is energized in series with the switching relay 858 of the connector H^2 . Relay 102, upon operating, disconnects the incoming trunk line from the dual connectors H^2 and H^2' and associates it with the conductors 970 and 972 at armatures 129 and 133 and at armature 132 places a busy potential upon

the jack J^3 which is accessible to the attendant operator. It will now be seen that by the energization of relay 858 in the connector switch H^2 a bridge is placed across the trunk conductors the circuit of which may be traced from bank contact 930, wiper 900, front contact and armature 893, armature 881 and its front contact, armature 889 and its back contact, upper winding of the impedance coil 853, armature 879 and its front contact, front contact and armature 880, lower winding of the impedance coil 853, front contact and armature 883, armature 897 and its front contact, wiper 902 to bank contact 932. The line relay 15 of the line switch C in the main exchange is energized over this circuit. Relay 15 upon operating completes a circuit of the pull down winding 1 of the line switch C. The line switch C now operates in the usual manner to extend the incoming trunk line into association with an idle first selector in the usual manner. The impedance coil 853, being included in the circuit of the line relay 15, is also energized but as the relay 854 is now operated, does not operatively attract its armature at this time.

The subsequent operations by which connection is established to the desired called subscriber's line in the main exchange will take place in the usual manner upon the calling device at substation A⁴ being operated in accordance with the digits of the desired subscriber's number. The impulses are repeated to the automatic switches in the main exchange by line relay 850 of the local connector H^2 at armature 873. When the conversation is terminated the release of the operated switches will take place in the usual manner upon the subscriber at substation A⁴ replacing his receiver upon the switchhook.

Had the main exchange been operating manually when the outgoing call was made by the subscriber at substation A⁴ the line relay 36 associated with the trunk line in the main exchange would be energized and the line lamp L' lighted. By the operation of this signal the main exchange operator would be notified that a main exchange connection is desired and she would insert the plug of an idle cord circuit into the jack J and operate her listening key. When the plug of the cord circuit is inserted into the jack J a circuit is thereupon completed over the sleeve of the plug for cut off relay 34. Relay 34, upon energizing, opens the circuit of the line relay 36 at armatures 40 and 41 and at armature 42 completes a circuit for the slow acting relay 37. It should be noted at this point that the slow acting relay 35 is so adjusted that it does not energize in series with the line relay 36. The main exchange operator may now extend the connection to the line of a main exchange subscriber in

the well known manner. When the conversation is terminated the called subscriber in the main exchange will replace his receiver upon the switchhook. Assuming that this occurs prior to the time the subscriber in the private automatic exchange replaces his receiver upon the switchhook the operator will receive the disconnect signal from the called subscriber and she will withdraw the plugs of the cord circuit from the jack of the called line and also from the jack J. By the latter operation the cut off relay 34 is deenergized. The line relay 36 is immediately energized over two sides of the trunk line in series and operates to complete the locking circuit of the slow acting relay 37. The line lamp L' is thereby prevented from operating and a busy potential is placed upon the jack J over a circuit which extends from battery through the resistance 47. The resistance in series with its battery is high enough so as to prevent the energization of the marginal relay 34. The trunk line comprising conductors 51 and 52 is now rendered busy until the subscriber at substation A⁴ in the private automatic exchange replaces his receiver upon the switchhook. At such a time the line relay 36 is deenergized and the locking circuit of the relay 37 is opened and the equipment associated with the trunk line in both the main and branch exchange is rendered ready for use by another subscriber.

In order to call the main exchange the attendant operator in the private automatic exchange is provided with two cord circuits one of which is shown in Fig. 17 and is adapted to be used when the main exchange is operating automatically. The other is shown in Fig. 21 and is adapted to be used when the main exchange is operating manually. In order to describe the operation of these two cord circuits it will be assumed that the attendant operator desires to establish a connection in the main exchange when it is operating automatically. In order to do this she will insert the calling plug P³⁶ of the cord circuit shown in Fig. 17 into the jack of an idle incoming trunk line. It will be assumed that the trunk line comprising conductors 51 and 52 is idle at the time the operator attempts to make a main exchange call and that she inserts the plug P³⁶ into the jack J². When this occurs a circuit is completed for the sleeve of the jack for the cut off relay 101 in series with the relay 1250. Relay 101 upon operating associates the incoming trunk line with the cord circuit shown in Fig. 17. Relay 1250 upon energizing completes a circuit for the polarizing winding of the electropolarized relay 1251. The operator will now throw her calling out key K³³ and operator calling device in accordance with the digits of the

main exchange subscriber's number. When the plug P^{36} is inserted into the jack J^3 the line switch C associated with the incoming trunk line in the main exchange is operated 5 in order to extend the trunk line to an idle first selector switch.

In response to the operations of the calling device in the cord circuit the switches in the main exchange are operated in order 10 to complete the connection to a called subscriber's line. When the called subscriber answers battery is reversed over the trunk line comprising conductors 51 and 52 and the electropolarized relay 1251 is immediately 15 operated in order to complete the circuit of the lamp L^{30} . This signal serves to notify the attendant of the response of the called subscriber and the operator in order to communicate with him will operate her listening key K^{34} . Upon the termination of the 20 conversation, the release of the operated switches will take place upon the operator withdrawing her plug P^{35} from the jack J^3 .

An alternative method which the attendant operator may use to establish an outgoing connection when the main exchange is operating automatically will now be briefly described. In this case the attendant operator will operate the calling out key similar 30 to the key K^5 associated with an idle trunk line. Assuming that the key K^5 is operated a circuit is completed extending from ground, by way of armature 135 and its back contact, back contact and armature 131, 35 back contact and armature 125, working contact of spring 130 and the said spring, and thence through the winding of relay 100 to battery. Relay 100, upon energizing, disconnects the incoming trunk line 40 comprising conductors 51 and 52 from the dual connectors H and H' and places a bridge across them which includes the operator's calling device. The line switch C associated with this trunk line in the main 45 exchange is immediately operated to extend the connection to an idle selector switch. In response to the operation of the calling device the connection to a desired subscriber in the main exchange will take place in the 50 usual manner.

Had the main exchange been operating manually the attendant operator would have used a cord circuit similar to the one shown in Fig. 21. The operation of this cord circuit will now be described, it being assumed in this case that the trunk line comprising conductors 51 and 52 is idle and that the operator has inserted the plug P^{37} in the pack J^3 in order to call the main exchange operator. When this occurs cut off relay 101 is energized and the relay 1302 is placed in a bridge across the trunk conductors. The line relay 36 is immediately operated and the line lamp L' lighted. Relay 1302 is also energized over the line cir-

cuit and operates to complete the circuit of the supervisory lamp L^{37} . The main exchange operator, upon noting the operation of the signal L' will insert the answering plug of an idle cord circuit into the jack J . 70 By this operation the circuit is completed for the cut off relay 34. The main exchange operator by throwing her listening key will be placed in communication with the attendant operator in the private automatic exchange and she will be able to give her any information desired. When the conversation is terminated the main exchange operator may withdraw the plug of the cord circuit from the jack J . - Assuming that the trunk line terminating in the jack J^8 is the first idle trunk line the operator will insert the plug P^4 into the jack and operate her calling device key K^{24} . By the former operation a circuit is completed extending from ground by way of the sleeve of the cord, armature 727 and its front contact, and through the winding of the slow acting relay 725 to battery. Relay 725, upon energizing, establishes a locking circuit for itself at armature 775 and places the polarized relay 726 across a bridge of the trunk conductors at armature 756. The line switch C^7 associated with the trunk line in the private automatic exchange is operated to extend the trunk line to an idle first selector switch in the usual manner. When the calling device is operated in accordance with the digits of the called subscriber's number, after first operating key K^{24} the selected selector and first connector are operated in order to extend the connection to the line of the subscriber at substation A^8 . After operating her calling device in accordance with the digits of the called subscriber's number the attendant operator in the private branch exchange will restore her calling device key K^{24} .
- When the called subscriber at substation A^8 answers battery is reversed over the trunk conductors and the polarized relay 726 operates its armature in a reverse direction. By this operation the circuit of the supervisory lamp L^{12} is completed and its operation serves to notify the private branch exchange operator that the called subscriber has answered. When the conversation is terminated both subscribers will replace their receivers upon their respective switch-hooks, the relays 726 and 752 will retract their armatures and the supervisory lamps L^{12} and L^{33} will be extinguished. By the effacement of these lamps the attendant operator in the private branch exchange will be notified of the disconnection and she will withdraw the plugs P^4 and P^5 of the cord circuit O' from their associated jacks. In this manner all the apparatus is restored to normal. It will be noted that had the subscriber at substation A^7 hung up prior to the subscriber at substation A^8 the circuit of the slow acting relay 725 would be opened and the relay would deenergize removing the polarized relay 726 from the bridge of the trunk conductors. By this operation the circuit of the line relay of the operated connector is broken and the switches in the private automatic exchange are immediately released.
- It will be quite obvious that the two way trunk line extending from the branch to the private automatic exchange could very readily terminate at the attendant operator's position instead of in the line switch C^7 . Assuming this to be the case, when a connection is made to a local subscriber's line through the medium of the cord circuit O' to the attendant operator's position and the subscriber in private branch exchange hangs up his receiver the polarized relay in the cord circuit O' is removed from bridge of the trunk circuit at the private branch exchange. By this operation the attendant operator in the private automatic exchange would be notified of the disconnection of the local subscriber in the private branch exchange.
- Had the attendant operator in the private branch exchange found that the subscriber at substation A^7 desires a connection with another branch exchange subscriber she would withdraw the plug P^5 from the jack J^9 and use a cord circuit shown in Fig. 19. When the plug P^{39} is inserted into the jack J^9 relays 1153 and 753 are energized in series. The relay 1152 is energized over the calling subscriber's line loop. The attendant operator will now test the jack associated with the desired called line by means of the tip of her plug P^{40} and if it is idle will insert the plug into the jack. By this operation the relay 1150 is energized over the sleeve of the jack. The latter relay, upon operating, completes the circuit for the supervisory lamp L^{33} . The operator will now throw her ringing key K^{36} in order to signal a called subscriber. When the called party answers the relay 1151 will be energized and the supervisory lamp L^{33} extinguished. When the subscribers have finished their conversation they will replace their receivers upon the switchhooks. The relays 1151 and 1152 are accordingly energized and the lamps L^{33} and L^{34} operate. By these signals the attendant operator in the private branch exchange is notified that conversation is terminated and she will withdraw the plugs of the cord circuit shown in Fig. 19 from their associated jacks.
- Having fully described and ascertained the features of the invention what is considered to be new and desired to have protected by Letters Patent will be pointed out in the appended claims.
- What I claim as my invention is:
- In a telephone system, a trunk line extending from a first to a second exchange and terminating at said second exchange in a pair of independently operable automatic connecting switches, a plug companionably associated with said trunk line at said second exchange, called lines in said second exchange, a group of said called lines accessible to said pair of automatic switches, the remainder of said called lines being accessible to said plug through the medium of jacks.
  - In a telephone system, a trunk line extending from a first to a second exchange and terminating at said second exchange in

a pair of independently operable automatic connecting switches, said trunk line extending through an operator's position at said second exchange, a plug companionably associated with said trunk line at said second exchange, called lines in said second exchange, a group of said called lines accessible to said pair of automatic switches, and the remainder of said called lines being accessible through the medium of jacks to said plug.

3. In a telephone system, a trunk line extending through an operator's position and terminating in a pair of independently operable automatic connecting switches, called lines accessible to said pair of automatic switches, a plug companionably associated with said trunk, other called lines terminating in jacks at said operator's position, means for seizing said trunk line and for operating one or the other switch of said pair into connection with one of said called lines, and means controlled by the operator at the said position for connecting said trunk line with one of said other subscriber's lines by way of said plug.

4. In a telephone system, a trunk line extending from a first exchange to a second exchange, a plug associated with said trunk line at said second exchange, a called line having talking conductor terminals and a busy-test terminal for indexing a busy condition of the called line accessible to said plug, means for connecting said plug and said called line, means for seizing said trunk line, and automatic means responsive to such seizure for applying ringing current to the connected called line and for causing the busy-test terminal to thereupon index a busy condition of the called line.

5. In a telephone system, a trunk line extending from a first exchange to a second exchange, a plug associated with said trunk line at said second exchange, a called line having talking conductor terminals and a busy-test terminal for indexing a busy condition of the called line accessible to said plug, means for connecting said plug and said called line, means for seizing said trunk line, means responsive to such seizure for applying ringing current to the connected called line and for causing the busy-test terminal to thereupon index a busy condition of the called line, and means responsive to the answer of the subscriber on the said called line for disconnecting said ringing current.

6. In a telephone system, a trunk line extending from a first to a second exchange, a plug associated with said trunk line at said second exchange, a called line having talking conductor terminals and busy-test terminals for indexing a busy condition of the called line accessible to said plug, means for connecting said plug and said line, means

for seizing said trunk line, and means responsive to such seizure for applying ringing current to said called line and for causing the busy-test terminal to thereupon index a busy condition of the called line.

7. In a telephone system, a trunk line extending from a first to a second exchange, a plug associated with said trunk line at said second exchange, a called line having talking conductor terminals and a busy-test terminal for indexing a busy condition of the called line associated with said plug, means for seizing said trunk line, means responsive to such seizure for applying ringing current to said called line and for causing the busy-test terminal to thereupon index a busy condition of the called line, and means responsive to the answer of the subscriber on the said called line for disconnecting said ringing current.

8. In a telephone system, a trunk line extending from a first exchange to a second exchange, a plug associated with said trunk line at said second exchange, subscribers' lines each having talking and busy-test conductors terminating in jacks at an operator's position, means for connecting said plug with one of said jacks, means for seizing said trunk line in said first exchange, and automatic means then operative for signalling the subscriber on the line with which the said plug is connected and for causing the busy-test conductor thereof to manifest a busy state of its line.

9. In a telephone system, a trunk line extending from a first exchange to a second exchange, a plug associated with said trunk line in said second exchange, subscribers' lines each having talking and busy-test conductors terminating in jacks at an operator's position, means under the control of the operator at said position for connecting said plug with one of said jacks, means for seizing said trunk line in said first exchange, automatic means then operative for signalling the subscriber on the line with which the said plug is connected and for causing the busy-test conductor thereof to manifest a busy state of its line and means operative when the subscriber on said line answers for cutting off said signalling.

10. In a telephone system, a trunk line extending from a first exchange to a second exchange, a plug associated with said trunk line in said second exchange, subscribers' lines terminating in jacks at an operator's position, means for connecting said plug with one of said jacks, an automatic switch for seizing said trunk line in said first exchange, and means in the second exchange operative in response to such seizure for applying ringing current to the line with which the said plug is associated.

11. In a telephone system, a trunk line extending from a first to a second exchange

and terminating in an automatic switch at busying said other trunk lines in said first said second exchange, subscribers' lines accessible to said automatic switch, a plug associated with said trunk line, means for connecting said plug to one of said subscribers' lines, means for seizing said trunk line in said first exchange, means in the second exchange then operative for applying ringing current to the line connected to said 5 plug, and a relay energized when the subscriber on said line answers for disconnecting said ringing current.

12. In a telephone system, a trunk line extending from a first to a second exchange 15 and terminating there in an automatic switch, a cord circuit at said second exchange, called lines, means for connecting said trunk line with one of said called lines by way of said cord circuit, means for seizing said trunk line at said first exchange, means responsive to such seizure for applying ringing current to the connected called line, means for then operating said automatic switch into connection with another 20 25 of said called lines and means responsive to such operation for disconnecting said ringing current from said connected called lines.

13. In a telephone system, a trunk line extending from a first to a second exchange 30 and terminating at said second exchange in an automatic switch, called lines, a cord circuit for connecting said trunk line with one of said called lines, means for seizing said trunk line and for operating said automatic 35 switch, means responsive to the seizure of said trunk line for applying ringing current to the connected called line, and means responsive to the operation of said automatic switch for disconnecting said trunk line 40 from the associated called line.

14. In a telephone system, a trunk line extending from a first to a second exchange and terminating at said second exchange in an automatic switch, called lines, a cord 45 circuit for connecting said trunk line with one of said called lines, means for seizing said trunk line and for operating said automatic switch, means responsive to the seizure of said trunk line for applying ringing 50 current to the connected called line, and means responsive to the operation of said switch for disconnecting said ringing current from said connected called line.

15. In a telephone system, trunk lines extending from a first to a second exchange, 55 one of said trunk lines terminating in an automatic switch at said second exchange, called lines, a cord circuit for connecting the trunk line terminating in said automatic 60 switch with one of said called lines, means for associating said connected trunk line with said other trunk lines, means for seizing said connected trunk line in said first exchange and for operating said automatic 65 switch, means responsive to such seizure for

busying said other trunk lines in said first exchange and for applying ringing current to the connected called line, and means responsive to the operation of said switch for removing the busy potential from said other 70 trunk lines at said first exchange and for disconnecting said ringing current from said connected called line.

16. In a telephone system, trunk lines extending from a first to a second exchange, 75 one of said trunk lines terminating in an automatic switch at said second exchange, means for associating the trunk line terminating in said automatic switch with said other trunk lines, means for seizing said 80 trunk line and for operating said automatic switch, means responsive to the seizure of said trunk line for busying said other trunk lines in said first exchange, and means responsive to the operation of said switch for removing the busy potential from said other 85 trunk lines in said first exchange.

17. In a telephone system, trunk lines extending from a first to a second exchange, 90 one of said trunk lines terminating in an automatic switch at said second exchange, means for seizing said trunk line terminating in said switch and for operating said automatic switch, means responsive to the seizure of said trunk line for busying said 95 other trunk lines in said first exchange, and means responsive to the operation of said switch for removing the busy potential from said other trunk lines in said first exchange.

18. In a telephone system, a trunk line 100 extending from a first to a second exchange, called lines at said second exchange, an operator's position, a cord circuit at said position for connecting said trunk line with one of said called lines each of which has talking terminals and a busy-test terminal, means for seizing said trunk line, means responsive to such seizure for applying ringing current to the connected called line and for causing the busy-test terminal to manifest a busy state of the line, a relay energized upon the response of the subscriber on the connected called line for disconnecting said ringing current, and means under the control of the operator at the said position for again connecting ringing current to said connected called line.

19. In a telephone system, a trunk line extending from a first to a second exchange, a plug associated with said trunk line in 105 said second exchange, a called line associated with said plug, other called lines, means for seizing said trunk line and for signalling the subscriber on the associated called line, and automatic means for then 110 extending the connection to include another of said called lines.

20. In a telephone system, a trunk line extending from a first to a second exchange, a plug associated with said trunk line in 115 120

said second exchange, a called line associated with said plug, other called lines, means for seizing said trunk line and for signalling the subscriber on the associated called line, and automatic means controlled by the subscriber on the associated called line for then extending the connection to include one of said other called lines.

21. In a telephone system, a trunk line
extending from a first to a second exchange,
a plug associated with said trunk line in
said second exchange, a called line associ-
ated with said plug, other called lines,
means for seizing said trunk line and for
15 signalling the subscriber on the associated
called line, automatic means controlled by
the subscriber on the associated called line
for then extending the connection to include
one of said other called lines, and means for
29 disconnecting the first called line from said
extended connection.

completely disconnecting said first called
line from said extended connection and for 75
rendering it accessible to other calls.

26. In a telephone system, a trunk line
extending from a first to a second exchange,
a plug associated with said trunk line in
said second exchange, a called line associ-
ated with said plug, other called lines,
means for seizing said trunk line and for
signalling the subscriber on the associated
called line, automatic means controlled by
the subscriber on the associated called line
for then extending the connection to include 80
65

40 23. In a telephone system, a trunk line extending from a first to a second exchange, a plug associated with said trunk line in said second exchange, a called line associated with said plug, other called lines, means for seizing said trunk line and for signalling the subscriber on the associated called line, automatic means controlled by the subscriber on the associated called line for then extending the connection to include one of said other called lines, and means controlled by the subscriber on said first called line for disconnecting the first called line from said extended connection.

45 28. In a telephone system, a trunk line extending from a first to a second exchange, a plug associated with said trunk line in said second exchange, a called line associated with said plug, other called lines, means for seizing said trunk line and for signalling the subscriber on the associated called line, automatic means controlled by the subscriber on the associated called line for then extending the connection to include one of said other called lines, and means controlled by the subscriber on said second called line for disconnecting the subscriber on said second called line from said connection.

50 24. In a telephone system, a trunk line extending from a first to a second exchange, a plug associated with said trunk line in said second exchange a called line associated with said plug other called lines, means for seizing said trunk line and for signalling the subscriber on the associated called line, automatic means controlled by the subscriber on the associated called line for then extending the connection to include one of said other called lines, and means for completely disassociating said first called line from said extended connection.

55 25. In a telephone system, a trunk line extending from a first exchange to a second exchange, a plug associated with said trunk line in said second exchange, subscribers' lines terminating in jacks at an operator's position, means for connecting said plug with one of said jacks, an automatic switch associated with said trunk line in said second exchange, means for seizing said trunk line in said first exchange, means then operative

65 25. In a telephone system, a trunk line extending from a first to a second exchange, a plug associated with said trunk line in
130 a said first exchange, means on said line for signalling the subscriber on the line with which the said plug is associated and means under the control of the subscriber on the

connected line for operating said automatic switch.

30. In a telephone system, a trunk line extending from a first to a second exchange, 5 a plug associated with said trunk line in said second exchange, subscribers' lines, means for connecting said plug with one of said subscribers' lines, means for seizing said trunk line in said first exchange, means then 10 operative for signalling the subscriber on said associated line, and means for extending the connection to another of said subscribers' lines.

31. In a telephone system, a trunk line 15 extending from a first to a second exchange, a plug associated with said trunk line at said second exchange, a called line accessible to said plug, means for connecting said called line and said plug, an automatic 20 switch having access to said called line, means for operating said automatic switch into connection with said called line, and means then operative for applying a busy potential to said trunk line in said first 25 exchange.

32. In a telephone system, a trunk line extending from a first to a second exchange, subscribers' lines, automatic switches, means for connecting said trunk line to one of said 30 subscribers' lines, means under the control of a subscriber on another of said lines for operating one of said automatic switches into connection with the line connected to said plug, and means then operative for 35 busying said trunk line in the first exchange.

33. In a telephone system, a trunk line extending from a first to a second exchange and terminating in an automatic switch, called lines accessible to said automatic 40 switch, means for seizing said trunk line and for operating said switch into connection with one of said called lines, a relay energized upon the response of the subscriber on the said called line, means controlled by said 45 relay for reversing the direction of current flow over said trunk line, and mechanical means for delaying the restoration of said normal battery flow to said trunk line after the subscriber on said called line hangs up.

50. 34. In a telephone system, a trunk line extending through an operator's position and terminating in an automatic switch, called lines accessible to said automatic switch, means for seizing said trunk line and for 55 operating said automatic switch into connection with one of said called lines, a relay energized upon the response of the subscriber on said called line, a solenoid for reversing the direction of current flow over said trunk line, and a circuit for said solenoid completed by the operation of said 60 relay.

35. In a telephone system, a trunk line extending from a first to a second ex-

change and terminating in a pair of automatic switches, called lines accessible to said switches, means for seizing said trunk line and for operating either of said pair of switches into connection with one of said called lines, a relay for reversing the direction of current flow over said trunk line, a circuit for said relay completed upon the subscriber on the said called line removing his receiver, and slow acting mechanical means for retarding the restoration of the 70 normal battery flow to said trunk line when the subscriber on said called line replaces his receiver upon the switchhook. 75

36. In a telephone system, a trunk line extending through an operator's position and terminating in a pair of automatic switches, called lines accessible to said pair of switches, means for seizing said trunk line and for operating either switch of said pair into connection with one of said called lines, 80 means at said operator's position actuated upon the response of the subscriber on said called line for reversing the direction of current flow over said trunk line, and means 85 for delaying the restoration of the normal battery flow to said trunk line when the subscriber on the said called line replaces his receiver upon the switchhook. 90

37. In a telephone system, a trunk line extending through an operator's position and terminating in a pair of automatic switches, called lines accessible to said switches, means for seizing said trunk line and for operating one switch of said pair into connection with one of said called lines, 95 a relay at said operator's position for reversing the direction of current flow over said trunk line, a slow acting solenoid for energizing said relay, a circuit for said solenoid completed upon the response of the subscriber on said called line, and mechanical means for delaying the restoration of said solenoid after the subscriber on the said called line replaces his receiver upon 100 the switchhook. 105

38. In a telephone system, a trunk line extending from a first to a second exchange and terminating in an automatic switch, called lines accessible to said automatic switch, means for seizing said trunk line and for operating said switch into connection with one of said called lines, a relay energized upon the response of the subscriber on the said called line, means controlled by said relay for increasing the current flow over said trunk line, and mechanical means for delaying the restoration of said normal battery flow after the subscriber on said called line hangs up. 110

39. In a telephone system, a trunk line extending through an operator's position and terminating in an automatic switch, called lines accessible to said automatic

- switch, means for seizing said trunk line and for operating said automatic switch into connection with one of said called lines, a relay energized upon the response of the subscriber on said called line, a solenoid at said operator's position for increasing the current flow over said trunk line, and a circuit for said solenoid completed by the operation of said relay.
40. In a telephone system, a trunk line extending through an operator's position and terminating in a pair of automatic switches, called lines accessible to said switches, means for seizing said trunk line and for operating one switch of said pair into connection with one of said called lines, a relay at said operator's position for increasing the current flow over said trunk line, a slow acting solenoid for controlling said relay, a circuit for said solenoid completed upon the response of the subscriber on the said called line, and mechanical means for delaying the restoration of said solenoid after the subscriber on the said called line replaces his receiver upon the switchhook.
41. In a telephone system, a trunk line terminating in a pair of automatic switches, called lines accessible to said switches, means for seizing said trunk line and for operating one switch of said pair into connection with one of said called lines, means under the control of the subscriber on the connected called line for operating the other switch of said pair into connection with another of said called lines, and a relay operated in response to the answer of the subscriber on the second called line for reversing the normal direction of current flow over said first called line.
42. In a telephone system, calling and called lines, automatic switches, means under the control of a subscriber on one of said calling lines for operating one of said automatic switches into connection with one of said called lines over a seriesed path including the calling line talking conductors, means for making the latter said line busy before being tested, and a relay in said switch responsive to such busy condition for releasing said switch and for placing a busy tone on the said calling line for the first time after said switch has been seized.
43. In a telephone system, a trunk line terminating in a pair of automatic switches, called lines accessible to said switches, means for seizing said trunk line and for operating one switch of said pair into connection with one of said called lines, means for making the latter said line busy before being tested, means responsive to such busy condition for releasing the operated switch and placing a busy tone on said trunk line, means for then operating the other switch of said pair into connection with another of said called lines, and means responsive to said last operation for removing said busy tone from said trunk line.
44. In a telephone system, a trunk line terminating in a pair of automatic switches, called lines accessible to said automatic switches, means for seizing said trunk line and for operating either switch of said pair into connection with one of said called lines, means for making the latter said line busy before being tested, and means responsive to said busy condition for releasing the operated switch of said pair.
45. In a telephone system, a trunk line terminating in a pair of automatic switches, called lines accessible to said switches, means for seizing said trunk line and for operating one switch of said pair into connection with one of said called lines, means for then operating the other switch of said pair into connection with another of said called lines, means for making the latter said called line busy before being tested, and a relay responsive to such busy condition for releasing the said other switch of said pair.
46. In a telephone system, a trunk line terminating in a pair of connector switches, called lines accessible thereto, means for seizing said trunk line and for operating one switch of said pair into connection with one of said called lines, means under the control of the subscriber on said called line for operating the other switch of said pair into connection with another of said called lines, means for making said last called line busy before being tested, means responsive to such busy condition for releasing said other switch and for placing a busy tone on said trunk line, means under the control of the subscriber on said first called line for reoperating said other switch into connection with a third one of said called lines and means responsive to said last operation for removing the busy tone from said trunk line.
47. In a telephone system, a trunk line terminating in a pair of automatic switches, called lines accessible to said automatic switches, another automatic switch having access to said called lines, means for seizing said trunk line and for operating one or the other switch of said pair into connection with one of said called lines, means under the control of the subscriber on said called line for rendering his line inaccessible to said pair of automatic switches, and means for then operating said other switch into connection with said called line.
48. In a telephone system, a trunk line extending through an operator's position and terminating in an automatic switch, a called line accessible to said switch, means for seizing said trunk line and for operating said switch into connection with said called line, means for rendering said line inaccessible to said switch, means for signalling the

operator at said position, and operator controlled means for operating said switch into connection with said line.

49. In a telephone system, a trunk line extending through an operator's position and terminating in a pair of automatic switches, called lines accessible to said pair of automatic switches, means for seizing said trunk line and for operating one switch of said pair into connection with one of said called lines, means under the control of the subscriber on another of said called lines for rendering his line inaccessible to the other switch of said pair, and means controlled by the operator at said position for operating the said other switch of said pair into connection with said other called line.

50. In a telephone system, an automatic switch, a called line accessible thereto, two groups of calling lines, means whereby the subscribers on the calling lines of one group may operate said automatic switch into connection with said line and means optionally controlled by the subscriber on said called line for rendering his line inaccessible to said automatic switch when controlled by a subscriber in the other group of said calling lines.

51. In a telephone system, a calling line, a trunk line terminating in a pair of automatic switches, called lines accessible thereto, means under the control of the subscriber on said calling line for seizing said trunk line and for operating one switch of said pair into connection with one of said called lines, means under the control of either the subscriber on said calling line or the subscriber on said called line for operating the other switch of said pair into connection with another of said called lines, and means for rendering said line inaccessible to the other switch of said pair when controlled by the subscriber on said calling line.

52. In a telephone system, a calling line, a trunk line terminating in a pair of automatic switches, called lines accessible thereto, means under the control of the subscriber on said calling line for seizing said trunk line and for operating one switch of said pair into connection with one of said called lines, means under the control of either the subscriber on said calling line or the subscriber on said called line for operating the other switch of said pair into connection with another of said called lines, and optionally controlled means for rendering said line inaccessible to the other switch of said pair when controlled by said calling subscriber.

53. In a telephone system, a calling line, a trunk line terminating in a pair of automatic switches, called lines accessible thereto, means under the control of the subscriber on said calling line for seizing said trunk

line and for operating one switch of said pair into connection with one of said called lines, means under the control of either the subscriber on said calling line or the subscriber on said called line for operating the other switch of said pair into connection with another of said called lines, and means optionally controlled by the subscriber on said another called line for rendering said line inaccessible to the other switch of said pair only when controlled by said calling subscriber.

54. In a telephone system, a calling line, a trunk line terminating in a pair of automatic switches, called lines accessible to said pair of switches, means under the control of the subscriber on said calling line for seizing said trunk line and for operating one switch of said pair into connection with one of said called lines, means under the control of either the subscriber on said calling line or the subscriber on said called line for operating the other switch of said pair into connection with another of said called lines, means under the control of the subscriber on said last called line for placing a test potential on his line, and means operable responsive to such test potential when said other switch is controlled by the subscriber on said calling line for releasing said other switch and placing a tone on said trunk line.

55. In a telephone system, a calling line, a trunk line terminating in a pair of automatic switches, called lines accessible to said pair of switches, means under the control of the subscriber on said calling line for seizing said trunk line and for operating one switch of said pair into connection with one of said called lines, means under the control of the subscriber on said called line for operating the other switch of said pair into connection with another of said called lines, and optionally controlled means operable when said other switch is controlled by the subscriber on said calling line for releasing said other switch and placing a tone on said trunk line.

56. In a telephone system, a calling line, a trunk line terminating in a pair of automatic switches, called lines accessible to said pair of switches, means under the control of the subscriber on said calling line for seizing said trunk line and for operating one switch of said pair into connection with one of said called lines, means under the control of the subscriber on said calling line for operating the other switch of said pair into connection with another of said called lines, and means controlled at the option of the subscriber on said second called line operable when said other switch is controlled by the subscriber on said calling line for releasing said other switch and placing a tone on said trunk line.

57. In a telephone system, a calling line,

- a trunk line terminating in a pair of automatic switches, called lines accessible to said pair of switches, means under the control of the subscriber on said calling line for seizing 5 said trunk line and for operating one switch of said pair into connection with one of said called lines, means under the control of either the subscriber on said calling line or the subscriber on said called line for operating 10 the other switch of said pair into connection with another of said called lines, and means only operable when said other switch is controlled by the subscriber on said calling line for releasing said other 15 switch.
58. In a telephone system, a calling line, a trunk line terminating in a pair of automatic switches, called lines accessible to said pair of switches, means under the control of 20 the subscriber on said calling line for seizing said trunk line and for operating one switch of said pair into connection with one of said called lines, means under the control of either the subscriber on said calling line or the subscriber on the said connected called 25 line for operating the other switch of said pair into connection with another of said called lines, and optionally controlled means operable only when said other switch is controlled by the subscriber on said calling line for releasing said other switch.
59. In a telephone system, a calling line, a trunk line terminating in a pair of automatic switches, called lines accessible to said 30 pair of switches, means under the control of the subscriber on said calling line for seizing said trunk line and for operating one switch of said pair into connection with one of said called lines, means under the control of the subscriber on said calling line for operating the other switch of said pair into connection with another of said called lines, and means controlled at the option of the subscriber on said second called line operable when said other switch is controlled by the subscriber on said calling line for placing a tone on said trunk line at its far end.
60. In a telephone system, a calling line, a trunk line terminating in a pair of automatic switches, called lines accessible to said 35 pair of switches, means under the control of the subscriber on said calling line for seizing said trunk line and for operating one switch of said pair into connection with one of said called lines, means under the control of the subscriber on said calling line for operating the other switch of said pair into connection with another of said called lines, and means controlled by the operator at said attendant's position for preventing the calling subscriber from operating either switch of said pair.
61. In a telephone system, a calling line, a trunk line terminating in a pair of automatic switches, called lines accessible to said 40 pair of switches, means under the control of the subscriber on said calling line for seizing said trunk line and for operating one switch of said pair into connection with one of said called lines, means for then operating the other switch of said pair into connection with a second called line, means under the control of the operator at the said position for preventing the operation of said automatic switch, and means then operative under the control of the operator at the said 45 position for operating one switch of said pair into connection with another of said called lines.
62. In a telephone system, a calling line, a trunk line terminating in a pair of automatic switches, called lines accessible to said 50 pair of switches, means under the control of the subscriber on said calling line for seizing said trunk line and for operating one switch of said pair into connection with one of said called lines, means under the control of the subscriber on said calling line for operating the other switch of said pair into connection with another of said called lines, and means controlled at the option of the subscriber on said second called line operable when said other switch is controlled by the subscriber on said calling line for barring connection of the said other switch to said second called line and placing a tone on said trunk line at its far end.
63. In a telephone system, a calling line, a trunk line extending through an attendant's position and terminating in a pair of automatic switches, called lines accessible to said 55 pair of switches, means under the control of the subscriber on said calling line for operating one switch of said pair into connection with one of said called lines, means for operating the other switch of said pair into connection with another of said called lines, and means controlled by the operator at said attendant's position for preventing the calling subscriber from operating either switch of said pair.
64. In a telephone system, a calling line, a trunk line extending through an operator's position and terminating in a pair of automatic switches, called lines accessible to said 60 pair of automatic switches, means under the control of the subscriber on said calling line for seizing said trunk line and for operating one switch of said pair into connection with one of said called lines, means for then operating the other switch of said pair into connection with a second called line, means under the control of the operator at the said position for preventing the operation of said automatic switch, and means then operative under the control of the operator at the said 65 position for operating one switch of said pair into connection with another of said called lines.
65. In a telephone system, calling and called lines, a trunk line extending from a

first to a second exchange, a pair of automatic switches associated with said trunk line in said second exchange, an attendant's position at said second exchange, means under the control of a subscriber on one of said calling lines for seizing said trunk line and for then operating one switch of said pair into connection with one of said called lines, means for then operating the other switch of said pair into connection with another of said called lines, and means under the control of the attendant at the said position for prohibiting the subscriber on said calling line from operating either switch of said pair.

66. In a telephone system, calling lines, a trunk line extending from a first to a second exchange, an attendant's position, an automatic switch associated with said trunk line, means under the control of one of said calling lines for seizing said trunk line and for operating said switch in accordance with a particular digit, and means then operative for signalling the operator at said attendant's position and for releasing said switch.

67. In a telephone system, a trunk line extending to an operator's position, a signalling device, an automatic switch adapted to be operated over two sides of said trunk line in series, a circuit for said signalling device closed by the operation of said automatic switch, and means for releasing said automatic switch when said signalling device is operated.

68. In a telephone system, a trunk line extending through an operator's position and terminating in an automatic switch, called lines accessible to said switch, means for operating said switch in accordance with a digit in a called number to select a group of lines, a signalling device at said operator's position, means for releasing said switch and operating said signalling device if said switch is operated in accordance with a particular digit.

69. In a telephone system, a trunk line extending through an operator's position and terminating in a pair of automatic switches, automatic means for seizing said trunk line and for transmitting operating impulses thereover to control one or the other of said automatic switches, a line signal at said operator's position, and a circuit for said line signal closed only by the operation of either of said automatic switches in response to a particular number of impulses.

70. In a telephone system, a trunk line extending through an operator's position and terminating in a pair of automatic switches, called lines accessible to said pair of automatic switches, means for seizing said trunk line and for operating one of said automatic switches into connection with one of said called lines, means whereby the sub-

scriber on said called line may operate the other switch of said pair in accordance with a particular digit, a line signal at said operator's position, and circuits closed by the operation of the other switch of said pair for operating said line signal and for releasing said switch.

71. In a telephone system, calling lines, a trunk extending through an operator's position and terminating in a pair of automatic switches, a line signal at said operator's position, called lines accessible to said automatic switches, means under the control of a subscriber on one of said calling lines for seizing said trunk line and for operating one switch of said pair into connection with one of said called lines, means under the control of either the subscriber on said calling line or the subscriber on said called line for operating the other switch of said pair, and circuits for operating said line signal and for releasing the other switch of said pair when said switch is operated in accordance with a particular digit by the subscriber on said calling line, said circuits operative when said other switch is operated in accordance with another digit by the subscriber on said called line.

72. In a telephone system, a trunk line extending from a first to a second exchange and terminating at said second exchange in a pair of automatic switches, calling lines in said first exchange, called lines accessible to said switches, means under the control of a subscriber on one of said calling lines for seizing said trunk line and for operating one of said automatic switches into connection with one of said called lines, means under the control of the subscriber on the calling line for then operating the other switch of said pair into connection with another called line, and means controlled by the response of the subscriber on the called line for preventing said calling subscriber from operating the said other switch.

73. In a telephone system, a trunk line terminating in an automatic switch, called lines accessible to said switch, one of said called lines extending to an operator's position, means for seizing said trunk line and for operating said automatic switch, a relay in said switch normally operative when the subscriber on one of said called lines answers for reversing the direction of current flow over said trunk line, and a mechanical interlocking device operative when said switch is operated into connection with said called line extending to said operator's position for preventing the operation of said relay.

74. In a telephone system, a trunk line terminating in an automatic switch, called lines accessible to said automatic switch, a group of said called lines leading to an operator's position, means for seizing said trunk line and for operating said automatic switch,

a relay in said switch normally operative when the subscriber on one of said calling lines answers for reversing the direction of current flow over said trunk line, and an interlocking device operative when said switch is operated into connection with one of said called lines extending to said operator's position for preventing the operation of said relay.

75. In a telephone system, calling and called lines, a cord for connecting one of said calling with a busy one of said called lines, and a relay responsive to such busy condition for disconnecting the operative connection of said lines.

76. In a telephone system, calling and called lines, a cord circuit for connecting said lines, and means responsive to a connection with a busy calling or a busy called line to disconnect the operative connection of the cord and the busy line connected with.

77. In a telephone system, calling and called lines, a cord circuit for connecting one of said calling lines with one of said called lines and a relay energized when the subscriber on the called line replaces his receiver upon the switchhook for disconnecting said cord circuit from the talking conductors of said connected called line.

78. In a telephone system, calling and called lines, a cord circuit for connecting one of said calling lines with one of said called lines, a relay energized upon the replacement of the receiver on the connected calling line for disconnecting said cord circuit from the talking conductors of said connected called line, and a second relay energized upon the replacement of the receiver on the connected called line for disconnecting said cord circuit from the talking conductors of said called connected line.

79. In a telephone system, a trunk line extending from a first to a second exchange, said trunk line extending through an operator's position at said second exchange, a relay associated with said trunk in said first exchange adapted when energized to apply a busy potential to said trunk line in said first exchange, and a key under the control of the operator at said position adapted to place a battery potential on one conductor of said trunk line to energize said relay.

80. In a telephone system, a trunk line extending from a first to a second exchange, said trunk line extending through an operator's position at said second exchange, a relay associated with said trunk in said first exchange adapted when energized to apply a busy potential to said trunk line in said first exchange, and a key under the control of the operator to energize said relay.

81. In a telephone system, an operator's position, calling lines terminating in jacks at the said position, a trunk line extending from said position terminating in an auto-

matic switch, called lines accessible to said automatic switch, means under the control of the operator at the said position for connecting a calling line with said trunk line and for then operating said automatic switch into connection with one of said called lines and means under the control of the subscriber on said calling line for releasing said automatic switch without destroying the calling state of the calling line.

82. In a telephone system, a trunk line, a calling signal operated by a relay at an answering end of the trunk, the energy for operating the relay emanating from a source at the answering end of the trunk, means for operating said relay and signal responsive to a call from the other end of the trunk, means for extending the answering end of the trunk toward a called line and effacing said signal, and means to prevent a reoperation of the signal if the called end extension is operatively disconnected before the calling end.

83. In a telephone system, a trunk line, a calling signal operated by a relay at an answering end of the trunk, the energy for operating the relay emanating from a source located at the answering end of the trunk, means for operating said relay and signal responsive to a call from the other end of the trunk, means for extending the answering end of the trunk toward a called line and effacing said signal, and means to prevent a reoperation of the signal if the called end extension is operatively disconnected before the calling end and whereby said signal cannot be reoperated from the calling end until an operative disconnection has been effected at the latter end.

84. In a telephone system, a telephone line terminating in a spring jack, a line signal, a line relay responsive to a call over said line for operating said signal and for applying a busy potential to said line, a cutoff relay for effacing said signal responsive to a connection with said jack, a busy relay for independently applying a busy potential to said line, means to prevent a reoperation of the line signal if disconnection from said jack is effected with the call still on the line and means controlled over the line for operating the latter said relay while the line is in a non-calling state.

85. In a telephone system, a telephone line terminating in a spring jack, a line signal, a line relay responsive to a call over said line for operating said signal and for applying a busy potential to said line, a cutoff relay for effacing said signal responsive to a connection with said jack, said cutoff relay restoring and said line relay again operating if disconnection from the jack is effected with the call still on the line, a busy relay for independently applying a busy potential to said line, means to prevent reoperation of

- the call signal when said line and cutoff relays are so operated and means controlled over the line for operating the latter said relay while the line is in a non-calling state. 5
86. In a telephone system, a telephone line terminating in a spring jack, a line signal, a line relay responsive to a call over said line for operating said signal and for applying a busy potential to said line, a cutoff relay for effacing said signal responsive to a connection with said jack, said cutoff relay restoring and said line relay again operating if disconnection from the jack is effected with the call still on the line, a busy relay for independently applying a busy potential to said line, means to prevent reoperation of the call signal when said line and cutoff relays are so operated until the call is effaced and means controlled over the line for operating the latter said relay while the line is in a non-calling state. 15
87. In a telephone system, a trunk line, line extensions for interchangeable connection to each end of the trunk, a calling signal and controlling circuit therefor at one end of the trunk primarily energized from a source at the latter said end to indicate when a calling line extension is connected to the other end of the trunk, means for effacing said signal when the signal end of the trunk is connected to a corresponding line extension, and means to prevent another call coming in by reoperation of said signal until the calling line extension is operatively disconnected from the trunk. 25
88. In a telephone system, a trunk line having a plug and jack connected extension at each end, a lamp signal operated by a relay at one end operative to indicate a call when connection is made to the other end of the trunk, the energy for operating the relay emanating from a source located at the answering end of the trunk, means for effacing the signal when the signal end is connected, and means to prevent another call coming in on said lamp signal until the plug at the other end of the trunk is withdrawn. 35
89. In a telephone system, an operator's switching cord pair, a trunk line extending from a spring jack and connected to one of the cord plugs, a holding circuit in the cord for maintaining the trunk circuit busy, means for connecting the other cord plug to a called line, and means operated upon response over the called line to transfer the holding circuit control to said called line. 45
90. In a telephone system, a trunk line, each end of which terminates in an operator's position, and means whereby the operator at one end of the trunk can place a false busy condition at the other end of the trunk so as to render the trunk busy to the operator at said other end. 55
91. In a telephone system, a trunk line terminating at one end in an operator's position, and means whereby the operator can place a false busy condition on the trunk at the other end thereof to render it non-selectable. 70
92. In a telephone system, a trunk line consisting of two talking conductors extending from a first exchange to corresponding terminals of a connecting plug in a second exchange, the two talking terminals of a called line accessible to the talking terminals of said plug, a busy-test terminal of said plug for registering with a busy-test terminal of said called line, means for seizing said trunk line at the first exchange, and automatic means responsive to such seizure for applying a busy potential to the busy-test terminal of the called line and for applying ringing current to the talking terminals of the said called line. 75
93. In a telephone system, a trunk line consisting of two talking conductors extending from a first exchange to corresponding terminals of a connecting plug in a second exchange, the two talking terminals of a called line accessible to the talking terminals of said plug, a busy-test terminal of said plug for registering with a busy-test terminal of said called line, means for seizing said trunk line at the first exchange, and automatic means responsive to such seizure for applying a busy potential to the busy-test terminal of the called line and for applying ringing current over one of the conductors of the called line. 80
94. In a telephone system, a trunk line extending from a first exchange to a second exchange, a plug associated with said trunk line at said second exchange, a called line accessible to said plug, means for connecting said plug with said called line without guarding the said called line against seizure otherwise, means for seizing said trunk line at the first exchange, means responsive to such seizure for applying guarding potential to the called line, and means responsive to the initiation of a call on the said called line for alternatively applying guarding potential to the called line. 85
95. In a telephone system, a trunk line extending from a first exchange to a second exchange, a plug associated with said trunk line at said second exchange, a called line accessible to said plug, means for connecting said plug with said called line without guarding the said called line against seizure otherwise, means for seizing said trunk line at the first exchange, means responsive to such seizure for applying guarding potential to the called line, and means responsive to the initiation of a call on the said called line for alternatively applying guarding potential to the called line and the trunk line at the first exchange end. 115
- 120
- 125
- 130

96. In a telephone system, a trunk line extending from a first exchange to a second exchange, a calling signal at the first exchange, a plug associated with the said trunk line at said second exchange, a called line accessible to said plug, means for connecting said plug with said called line without guarding the said called line against seizure otherwise, means for seizing said trunk line at the first exchange, means responsive to such seizure for applying guarding potential to the called line, and means responsive to the initiation of a call on the said called line for alternatively applying a guarding potential to the called line and for operating the said calling signal. 70

97. In a telephone system, a plurality of trunk lines extending from a first exchange to a second exchange, a plug associated with each said trunk line at said second exchange, called lines accessible to said plugs, means for connecting said plugs with a said called line respectively without guarding any of the said called lines against seizure otherwise, means for seizing a said trunk line at the first exchange, and means responsive to such seizure for applying guarding potential to its connected called line and to the other said connected called lines. 80

98. In a telephone system, a plurality of trunk lines extending from a first exchange to a second exchange, a plug associated with each said trunk line at said second exchange, called lines accessible to said plugs, means for connecting said plugs with a said called line respectively without guarding any of the said called lines against seizure otherwise, means for seizing a said trunk line at the first exchange, and means responsive to such seizure for applying guarding potential to its connected called line and to the other said connected called lines and to the first exchange end of the unseized trunk lines. 90

99. In a telephone system, a plurality of trunk lines extending from a first exchange to a second exchange, a plug associated with each said trunk line at said second exchange, called lines accessible to said plugs, means for connecting said plugs with a said called line respectively without guarding any of the said trunk lines against seizure at the first exchange end, means for seizing a said trunk line at the first exchange, and means responsive to such seizure for applying a guarding potential to all said trunk lines at the first exchange end. 100

100. In a telephone system, a plurality of trunk lines extending from a first exchange to a second exchange, a plug associated with each said trunk line at said second exchange, called lines accessible to said plugs, means for connecting said plugs with a said called line respectively without guarding any of the said trunk lines against seizure at the first exchange end, means for seizing any said trunk line at the first exchange by way of extending an independent talking connection from the first exchange over the seized trunk and connected called line, and means responsive to such seizure for applying a guarding potential to all said trunk lines at the first exchange end. 110

101. In a telephone system, a plurality of trunk lines extending from a first exchange to a second exchange, a plug associated with each said trunk line at said second exchange, called lines accessible to said plugs, means for connecting said plugs with a said called line respectively without guarding any of the said trunk lines against seizure at the first exchange end, means for seizing any said trunk line at the first exchange, and means at the second exchange end responsive to such seizure for applying a guarding potential to the said trunk lines at the first exchange end. 120

102. In a telephone system, a plurality of trunk lines extending from a first exchange to a second exchange for two-way switching, a plug associated with each said trunk line at said second exchange, called lines accessible to said plugs, means for connecting said plugs with a said called line respectively without guarding any of the said trunk lines against seizure at the first exchange end or the second exchange end, means for seizing any said trunk line at both exchange ends independently, and means responsive to a said seizure for applying a guarding potential to all said trunk lines at both exchange ends. 130

103. In a telephone system, a plurality of trunk lines extending from a first exchange to a second exchange, a plug associated with each said trunk line at the second exchange, called lines accessible to the said plugs, means for connecting said plugs with a said called line respectively without guarding any of the said trunk lines against seizure at the first exchange end, means for seizing any said trunk line at the first exchange by way of extending an independent talking connection from the first exchange over the seized trunk and connected called line, and means responsive to such seizure for applying a guarding potential to all said trunk lines at the first exchange end. 140

104. In a telephone system, a plurality of trunk lines extending from a first exchange to a second exchange, a plug associated with each said trunk line at the second exchange, called lines accessible to the said plugs, means for connecting said plugs with a said called line respectively without guarding any of the said trunk lines against seizure at the first exchange end, means for seizing any said trunk line at the first exchange by way of extending an independent talking connection from the first exchange over the seized trunk and connected called line, and means at the second exchange end responsive to such seizure for applying a guarding potential to the said trunk lines at the first exchange end. 150

tential to all said trunk lines at the first exchange end.

105. In a telephone system, a plurality of trunk lines extending from a first exchange to a second exchange for two-way switching, a plug associated with each said trunk line at said second exchange, called lines accessible to said plugs, means for connecting said plugs with a said called line respectively without guarding any of the said trunk lines against seizure at either end, means for seizing any said trunk line at the first and second exchange ends alternatively by way of extending an independent talking connection over the seized trunk and connected called line in one or the other direction, and means responsive to such seizure for applying a guarding potential to all said trunk lines at the first exchange end and the second exchange end simultaneously.

106. In a telephone system, a plurality of trunk lines extending from a first exchange to a second exchange, a plug associated with each said trunk line at said second exchange, called lines accessible to said plugs, means for connecting said plugs with said called lines respectively without guarding any of the said trunk lines against seizure at the first exchange end, means for seizing any said trunk line at the first exchange by way of extending an independent talking connection from the first exchange over the seized trunk line and connected called line, means responsive to such seizure for applying a guarding potential to all said trunk lines at the first exchange end, and means controlled from any said called line for applying a guarding potential to the exchange end of all said trunk lines simultaneously.

107. In a telephone system, trunk lines extending from a first to a second exchange, each of said trunk lines terminating in an automatic switch at said second exchange, means for associating the trunk lines, means for seizing any said trunk line at the first exchange and for thereafter operating its corresponding said switch in the second exchange, means responsive to the seizure of a said trunk line in the first exchange for operating means at the second exchange effective to busying the other trunk lines in the first exchange, and means responsive to the operation of the switch on the seized trunk line for removing the busy potential from the said other trunk lines in the first exchange.

108. In a telephone system, a trunk line extending through an operator's position and terminating in an automatic switch, a called line accessible to said switch, means for seizing said trunk line and for operating said switch into connection with said called line, means under control of the subscriber on the called line for rendering said line inaccessible to said switch, means oper-

ated independent of last said means controlled over the called line for signaling the operator at said position, and operator controlled means for operating said switch into connection with said line to complete a connection from the trunk to said called line.

109. In a telephone system, a trunk line extending through an operator's position and terminating in a pair of automatic switches, called lines accessible to said pair of automatic switches, means for seizing said trunk line and for operating one switch of said pair into connection with one of said called lines and thereafter operating the other switch of said pair with relation to another of said called lines, means under control of the subscriber on said another of said called lines for rendering his line inaccessible to the other switch of said pair, and means controlled by the operator at said position for operating the said other switch of said pair into connection with said other called line.

110. In a telephone system, a calling line, a trunk line terminating in a pair of automatic switches, called lines accessible thereto, means under control of the subscriber on said calling line for seizing said trunk line and for operating one switch of said pair into connection with one of said called lines, means under the control of either the subscriber on said calling line or the subscriber on said called line for operating the other switch of said pair into connection with another of said called lines, and means controlled by the subscriber on the said another of said called lines for rendering said line inaccessible to the said other switch of said pair when controlled by the subscriber on the said calling line.

111. In a telephone system, a calling line, a trunk line terminating in a pair of automatic switches, called lines accessible thereto, means under control of the subscriber on said calling line for seizing said trunk line and for operating one switch of said pair into connection with one of said lines, means under the control of either the subscriber on said calling line or the subscriber on said called line for operating the other of said pair into connection with another of said called lines, and optionally controlled means by the subscriber on the said another of said called lines for rendering the latter said line inaccessible to the said other switch of said pair when controlled by said calling subscriber.

112. In a telephone system, calling lines, a trunk line extending from a first to a second exchange, an attendant's position, an automatic switch associated with said trunk line, means under control of one of said calling lines for seizing said trunk line and for operating said switch in accordance with a particular digit, and means then automat-

ically operative for signaling the operator at said attendant's position and for releasing said switch.

113. In a telephone system, a trunk line extending to an operator's position, a signaling device, an automatic switch adapted to be operated over two sides of said trunk in series, a circuit for said signaling device closed by the operating of said automatic switch, and automatically applied means for releasing said automatic switch forthwith upon said signaling device being operated.

114. In a telephone system, a trunk line extending through an operator's position and terminating in an automatic switch, called lines accessible to said switch, means for operating said switch in accordance with a digit in a called number to select a group of lines, a signaling device at said operator's position, means for automatically releasing said switch and operating said signaling device if said switch is operated in accordance with a particular digit.

115. In a telephone system, calling and called lines, means for connecting one of said calling with a busy one of said called lines, and a relay automatically responsive to such busy condition for disconnecting the operative connection of said lines.

116. In a telephone system, calling and called lines, means for connecting said lines, and automatically applied means responsive to a connection with a busy calling or a busy called line to disconnect the operative connection effected by the first said means.

117. In a telephone system, a trunk line extending from a first to a second exchange, said trunk line terminating in an operator's position at said second exchange, a relay associated with a talking conductor of said trunk in said first exchange for applying a false guarding potential to said trunk line in said first exchange, and a key companion to the trunk at the operator's position for operatively energizing the relay while the trunk is free of call extensions.

118. In a telephone system, a trunk line extending from a first to a second exchange, said trunk line terminating in an operator's position at said second exchange, a relay associated with a talking conductor of said trunk in said first exchange for applying a false guarding potential to said trunk at the said first exchange, and a key companion to the trunk at the operator's position for applying a source of direct current over a talking conductor of the trunk line for operatively energizing the relay.

119. In a telephone system, a trunk line extending from a first to a second exchange, said trunk line terminating in an operator's position at said second exchange, a relay associated with a talking conductor of said trunk in said first exchange for applying a false guarding potential to said trunk line

in said first exchange during the time the relay is energized and for removing said guarding potential when the relay is de-energized, a key at the operator's position for applying a source of current over a talking conductor of the trunk operative to the relay, and an automatic means for also applying said source of current as by the said key.

120. In a telephone system, a trunk line extending from a first to second exchange, said trunk line terminating in an operator's position at said second exchange, a relay associated with a talking conductor of said trunk in said first exchange for applying a false guarding potential to said trunk line in said first exchange, and a key at the operator's position for applying a source of direct current over a talking conductor of the trunk line for operatively energizing the relay.

121. In a telephone system, a trunk line extending from a first to a second exchange, said trunk line terminating in an operator's position at said second exchange, a relay associated with a talking conductor of said trunk in said first exchange for applying a false guarding potential to said trunk line in said first exchange during the time the relay is energized and for removing said guarding potential when the relay is deenergized, and a key at the operator's position for applying a source of current to the trunk to energize the relay and for then removing said source from the trunk at the will of the operator to deenergize the relay.

122. In a telephone system, an operator's switching cord pair, a trunk line extending from a springjack connected with one of the cord plugs, a holding circuit in the cord for maintaining the trunk circuit in a responded state dependent upon the duration of the said connected state, means for connecting the other cord of said pair to a called line, and means operated consequent upon a response on the called line whereby if the responded state of the called line terminates the trunk circuit will cease to manifest a responded state regardless of the first said plug and springjack being maintained connected.

123. In a telephone system, a called line leading from a springjack, an operator's switching cord and plug pair, the talking conductors of the springjack normally presenting an open conductive path but presenting a closed conductive path when engaged, talking conductors of said plug adapted to register with the talking terminals of the springjack, a relay associated with one of the talking terminals of a said plug, the corresponding talking terminals of the plugs being normally connected in talking relation, a means for disconnecting the latter said connection controlled by the operation of the

relay, means whereby if the plug with which the relay is associated is connected to an engaged line the relay will operate, and means whereby if the plug is connected to an unengaged line the relay will not operate.

124. In a telephone system, a called line leading from a springjack, an operator's switching cord and plug, a cord circuit companion to the said cord and plug, the talking conductors of the said springjack normally presenting an open conductive path but presenting a closed conductive path when engaged, talking conductors of said plug adapted to register with the talking terminals of the springjack, a relay associated with one of the talking terminals of the said plug, the talking terminals of the plug being normally connected to the said companion cord circuit, a means for disconnecting the latter said connection controlled by the operation of the relay, means whereby if the plug is connected to an engaged line the relay will operate, and means whereby if the plug is connected to an unengaged line the relay will not operate.

125. In a telephone system, a trunk line and terminating automatic switch, a called line accessible to said switch, means for seizing said trunk line and for operating said switch into connection with said called line, means in control of the subscriber on the called line for rendering said line inaccessible to said switch, means operated independent of last said means controlled over the called line for signaling the operator at said position, and operator controlled means for operating said switch into connection with said line to complete a connection from the trunk to said called line regardless of the operated state of third said means.

126. In a telephone system, a trunk line, line extensions for interchangeable connection to each end of the trunk, a calling signal at one end of the trunk to indicate when a calling line extension is connected to the other end of the trunk, a source of current at said one end of the trunk, means controlled over the trunk from the end to which the calling line is connected for operating the signal device energized by said source, means for effacing said signal when the signal end of the trunk is connected to a corresponding line extension, and means to prevent another call coming in by reoperation of said signal until the calling line extension is operatively disconnected from the trunk.

127. In a telephone system, a trunk line, line extensions for interchangeable connection to each end of the trunk, a calling signal at one end of the trunk to indicate when a calling line extension is connected to the other end of the trunk, a source of direct current, means controlled over the trunk from the end to which the calling line is

connected for operating the signal device energized by said source, means for effacing said signal when the signal end of the trunk is connected to a corresponding line extension, and means to prevent another call coming in by reoperation of said signal until the calling line extension is operatively disconnected from the trunk. 70

128. In a telephone system, a two-conductor trunk line extending from a first exchange to a second exchange, a calling signal device for the trunk at the first exchange, means controlled over the trunk line for operating said signal at will, a guarding terminal for said trunk line at said first exchange, and means controlled over a conductor of the trunk for placing a guarding potential on said trunk at the first exchange without operating the calling signal device. 75 80

129. In a telephone system, a two-conductor trunk line extending from a first exchange to a second exchange, a calling signal device for the trunk at the first exchange, means controlled over the trunk line for operating said signal at will, a guarding terminal for said trunk line at said first exchange, and means controlled over a single conductor of the trunk for placing a guarding potential on said trunk at the first exchange without operating the calling signal device. 85 90

130. In a telephone system, a plurality of two-conductor trunk lines extending from a first exchange to a second exchange, a calling signal device for the respective trunk lines at the first exchange, a called line in the second exchange, a temporary co-existing connection between the respective trunks and the called line, guarding terminals for the respective trunks at the first exchange, means controlled over the respective trunks from the second exchange for operating only the corresponding signal device, and means controlled over the called line for placing a guarding potential on the respective trunks at the first exchange without operating any other said signal device while maintaining said connection. 100 105 110

131. In a telephone system, a two-conductor trunk extending from a first exchange to a second exchange, terminals for said trunk at the exchanges, a calling signal device for said trunk at said first exchange, means controlled over said trunk for operating said signal at will, a guarding terminal for said trunk at said first exchange, and means controlled over a conductor of said trunk for placing a guarding potential on said guarding terminal at the first exchange without operating said signal device. 115 120 125

132. In a telephone system, a two-conductor line extending to an exchange, line and busy guard terminals for said line at said exchange, a calling signal device for said line at the exchange, means controlled over

5 said line for operating said signal at will, means controlled over a conductor of said line for placing a guarding potential on said guard terminal at the exchange at will without operating said signal device, and means for removing said guarding potential without applying current over a conductor of said line.

10 133. In a telephone system, a two-conductor line extending to an exchange, line and busy guard terminals for said line at said exchange, a calling signal device for said line at the exchange, means controlled over said line for operating said signal at will, and means controlled over a conductor of said line for placing a guarding potential on said guard terminal at the exchange at will without operating said signal device.

15 134. In a telephone system, a two-conductor line extending to an exchange, line and busy guard terminals for said line at said exchange, call extending mechanism at the exchange, means controlled over said line for operating said mechanism at will, and means controlled at will over a conductor of said line for placing a guarding potential on said guard terminals at the exchange without operating said mechanism.

20 135. In a telephone system, a two-conductor line extending to an exchange, line and busy guard terminals for said line at said exchange, call extending mechanism at the exchange, means controlled over said line for operating said mechanism at will, means

25 controlled at will over a conductor of said line for placing a guarding potential on said guarding terminal at the exchange without operating said mechanism, and means for removing the guarding potential without applying current over a conductor of said line.

30 136. In a telephone system, a plurality of two-conductor trunk lines extending from line terminals in a first exchange to a second exchange, a plug associated with each said trunk line at said exchange, called lines accessible to said plugs, means for connecting said plugs with a said called line respectively without guarding any of the said trunk lines against seizure at the first exchange end, means for seizing at random said trunk line at the first exchange, and means responsive to such seizure for applying a guarding potential to auxiliary guarding terminals of all said trunk lines at the first exchange.

35 137. In a telephone system, calling and called lines, means for connecting one of said calling with a busy one of said called lines, and a relay automatically responsive to such busy condition and energized over one of the talking conductors of the connection for disconnecting the operative connection of said lines.

40 In witness whereof, I hereunto subscribe my name this 23rd day of April, A. D., 1921.

45 HERBERT M. FRIENDLY.
